ELECTRIC SIGNALING SYSTEM

Felix F. Denzler, Pomona, Calif.

Application December 8, 1933, Serial No. 701,447

47 Claims. (Cl. 177—360)

This invention relates broadly to electric signaling systems and has particular application to safety systems such as fire alarm and burglar alarm systems, although certain features of the invention may be used in other communication systems.

A broad object of the invention is to increase the reliability and usefulness of electric safety systems by making their operation less subject to interruption by line troubles, both those resulting from unavoidable causes and those maliciously caused.

Another object is to prevent any line fault that does not totally incapacitate the line for signaling purposes from transmitting a false alarm while at the same time giving an indication that there is trouble on the line, and connecting the line to an alarm circuit in a different manner so that the line is still effective to transmit a bona fide alarm should one be sent, while sending in an alarm in case the line is totally incapacitated.

Another object is to provide, in a burglar alarm system, means for restoring the local alarm circuit at a protected premises from a central station and to provide a signal at the premises to indicate to the occupant or a watchman that the circuit is in proper condition.

Another object is to provide a plurality of lines from an alarm system central station to fire or police headquarters with means for automatically supervising the lines from the central station to indicate the existence of trouble on any one of the lines to fire or police headquarters.

The attainment of the foregoing objects makes practicable a system employing existing line circuits of telephone and telegraph companies, which are more subject to trouble than specially made and protected alarm circuits, and also makes practicable the automatic relaying of alarms directly to fire or police headquarters without the use of an intermediate operator to ascertain whether an alarm is false or bona fide.

This is a continuation in part of my application Serial No. 639,329, filed October 24th, 1932 on 45 Electrical signaling systems, and now abandoned.

Various other objects and features of the invention will be apparent from the following detailed description which refers to the drawings.

In the drawings:

50 Fig. 1 is a schematic layout of an entire system in accordance with the invention;

Fig. 2 is a detail circuit diagram of that portion of a fire alarm system, in accordance with the invention, located at the protected premises P, 55 and on the supervisory panel SP associated with

that premises circuit but located at the central station;

Fig. 3 is a schematic circuit of the same portion of the system shown in Fig. 2, with certain switch contacts and auxiliary apparatus eliminated to 5 simplify the tracing of the main circuits;

Fig. 4 is a simplified schematic diagram of a modification of the premises circuit shown in Fig. 3;

Fig. 5 is a detail diagram of a subscriber's 10 premises and a subscriber's supervisory panel circuit in a burglar alarm system in accordance with the invention;

Fig. 6 is a simplified schematic circuit showing the most important features of the circuit in Fig. 15 with certain reset switches and auxiliary apparatus eliminated;

Fig. 7 is a detail schematic circuit showing a modification of the premises portion of the circuit shown in the schematic diagram of Fig. 6; 20

Fig. 8 is a schematic diagram of an automatic alarm code transmitter indicated at T in Figs. 1, 2, 3, 5 and 6; and

Fig. 9 is a detail diagram of a headquarters line supervisory panel circuit. 25

Referring to Fig. 1, a complete system in accordance with my invention, whether a fire alarm or burglar alarm system, comprises a plurality of sub stations at premises to be protected, the apparatus at each station comprising a group of 30 apparatus indicated at P having connected thereto a protection loop L which may extend throughout the premises, and being connected to a central station CS by a line SL. The lines SL are indicated with a single line in Fig. 1 but actually 35 each line comprises a pair of metallic conductors.

At the central station CS each line SL is connected through a subscriber's supervisory panel SP to a code transmitter T, which when actuated connects itself through an associated line finder 40 LF to any one of a plurality of lines HL extending to fire or police headquarters SD. At the headquarters SD each line HL connects to an individual alarm recorder AR. Each headquarters line HL also has associated therewith at its central station end a headquarters line supervisory panel HP, the function of which is to indicate to the line finders LF whether or not that particular headquarters line HL is in condition to transmit 45 an alarm.

The operation of my system will now be explained in detail with reference to the detail drawings of the various units L, P, SL, SP, T, LF, HP, HL and AR, shown schematically in 55 Fig. 1.

The code transmitter T, line finders LF, headquarters line supervisory panels HP, headquarters lines HL, and alarm recorders AR are the same in both the fire and burglar alarm systems. 5 However, the subscriber's loop circuits L, premises apparatus panels P, and subscriber's supervisory panels SP at the central station are different in the fire and burglar alarm systems, respectively.

Fire alarm system

- 10 Referring to Fig. 2, in my fire alarm system the equipment at the protected premises includes a loop L which comprises a pair of conductors 11 and 12, respectively, extending out of a control box P out over the premises and back into the control box P. A plurality of danger responsive devices 13 are bridged across the conductors 11 and 12 and are adapted to short circuit these conductors in case of a fire. Thus, 20 some of the devices 13 may be thermostatic devices located in various rooms in a building and adapted to short circuit the conductors 11 and 12 in response to a rise in temperature above a predetermined limit, and other of the devices 25 13 may be pull-boxes located at different points on the premises and adapted to be manually operated to short circuit the conductors 11 and 12.
- The control box P includes relays 1, 0 and 2, a resistor 14, a resistor 15, an alarm bell 16, and 30 a manually operated restoring key Z. The key Z is shown as two separate units to simplify the circuit connections but it actually comprises a plurality of contact members operated by a single handle. Relay 1 is a sensitive relay which 35 is fast to release when its operating circuit is interrupted. Relay 0 is a marginal relay which normally carries current of a predetermined value but remains unoperated until the current therethrough is increased above normal value. The 40 relay 0 is provided with a mechanical latch 17 which locks it up when it has once been pulled and maintains it locked until manually released by an operator. The relay 2 is a slow-release relay.
- 45 The line SL connecting the control box P at the protected premises to the subscriber's supervisory panel SP at the central station comprises two metallic conductors X and Y, respectively, as shown.
- 50 The subscriber's supervisory panel SP includes a pair of marginal relays 3 and 4, a sensitive fast release relay 8, a pair of slow release relays 6 and 7, a main battery 18, which may be common to all of the supervisory panels SP at the central 55 office, an auxiliary battery 19, a trouble alarm relay 10, a trouble alarm buzzer 20, a white signal lamp W, a red signal lamp R, a blue signal lamp B, current limiting resistors 21, 22 and 23, and a key A. Key A is shown in two sections to simplify the circuit connections but it is to be understood that it really consists of a single key having a single control handle. The marginal relay 0 is adjusted to operate before the marginal relays 3 and 4 and the slow release relay 2 is 60 designed to release faster than the slow release relays 6 and 7.

Key A in the subscriber's supervisory panel SP and key Z in the control box P at the subscriber's premises are used only to restore the 70 system to normal following the transmission of an alarm or the existence of trouble on the circuit. These keys can, therefore, be disregarded in following the normal operation of the circuit up to the reset operation. For this reason they 75 have been eliminated in the schematic circuit of

Fig. 3, to which reference is now made. Likewise, certain auxiliary circuits, including the alarm bell 16 in the control box P, the trouble alarm relay 10, and the signal lamps W, R and B have been eliminated from the circuit of Fig. 3.

As shown in Fig. 3, all the relays in the circuit are in their normal position waiting for an alarm. Under these conditions a closed circuit is completed from battery at the central station out over the line conductor X, through the control box P and loop L and back over the line conductor Y to ground at the supervisory panel SP. This circuit is shown in heavy lines and may be traced as follows: From battery 18 at the central station, through contacts T2 and F2 on relay 8, through contacts T2 and B2 on relay 4, through the winding of relay 4, through contacts T1 and B1 on relay 4, out over line X through contacts T1 and F1 of relay 2 and the winding of relay 2, to the loop conductor 11, 20 through the resistor 24 at the end of the loop, back over the loop conductor 12, through contacts F3 and T3 of relay 2, through the winding of relay 0, through the contacts T2 and B2 of relay 0, through contacts T3 and F3 on relay 1 25 and the winding of relay 1, out over line Y, through the contacts B4 and T4 and the winding of relay 3, contacts T2 and B2 of relay 3, contacts F4 and T4 and the winding of relay 8, the winding of relay 7, and over the contacts F5 30 and T5 of relay 8 to ground. (It will be observed that in the reference numerals on the various contacts in the circuit the letter prefix indicates the nature of the contacts. Thus where the contact number is preceded by the letter T, it means 35 that the contact is an armature contact or a transfer contact, where the number is preceded by the letter F, it means that the contact is a front contact, and where the number is preceded by the letter B, it means that the contact is a 40 back contact.)

The current flowing through the closed circuit traced from the battery 18 is normally limited to a predetermined value by proper adjustment of the resistance 24 at the end of the loop 45 conductors 11 and 12. This current value is sufficient to maintain relays 7 and 8 on the supervisory panel and relays 1 and 2 in the premises control box P operated but is insufficient to actuate the marginal relay 0 and the marginal relays 3 and 4. It will be observed that, 50 as long as relay 7 is operated, it closes an actuating circuit through its contacts T and F for the relay 6, thereby maintaining the latter operated. Relay 6 in turn closes a circuit from the 55 battery to the input leads 25 and 26 to the code transmitter T. The construction and operation of the code transmitter T will be described in detail later. It will suffice at this point to state that the code transmitter T is locked against 60 operation as long as battery is supplied to its input terminals 25 and 26.

Normal operation—Fire alarm system

When a fire alarm condition is created, as by 65 actuating one of the danger responsive devices 13, the loop conductors 11 and 12 are short circuited, thereby shunting the resistance 24 out of the circuit traced in heavy lines. This permits an increased current flow over the circuit 70 traced in heavy lines, which increased current is sufficient to actuate the relay 0 in the control box P and this relay upon being actuated is locked up mechanically by the latch 17. It will be observed that the actuation of relay 0 breaks 75

the circuit traced in heavy lines at the contacts T2 and B2 of relay 0, thereby causing an immediate release of relay 1 in the control box P and relay 8 on the supervisory panel SP. The circuits for relays 2 and 1 are also opened but those relays do not release immediately because of the fact that they are slow to release.

The release of relay 8 on the supervisory panel SP reconverts the circuit to connect the battery 18 directly through the winding of relay 7 to both sides of the line X and Y, respectively. This circuit may be traced as follows: From battery 18, over contacts T2 and B2 of relay 8, through the winding of relay 7, through the contacts T1 and B1 of relay 8, to the contact T2 of relay 4, and through the contacts B3 and T3 of relay 8, to the contact B2 of relay 3. From contact T2 on relay 4 the circuit continues as originally traced to the line conductor X. From contact B2 on relay 3 the circuit also continues as originally traced to the line conductor Y.

The net result is that following release of relay 8 battery is applied through relay 7 to both line conductors X and Y in parallel. If there is any path to ground from either conductor X or Y in the control box P, current flow will be resumed from battery 18 through the winding of relay 7 before the latter has had time to release. However, there can be no such flow of current from either line conductor X or Y to ground because the only path to ground in the control box is over the contact T1 of the relay 0 and, with relay 0 locked up in operated position, any ground path to either line conductor is open at contact B1 on relay 0. Referring for the moment to Fig. 2, it will be observed that the operation of relay 0 applies ground over contacts T1 and F1 to operate the alarm bell 16 in box P over a local circuit.

Since there is no path to ground over either line conductor X or Y, there can be no resumption of current flow from battery 18 through the winding of relay 7 and the latter finally releases its armature, opening the actuating circuit of relay 6. Relay 6 is also a slow release relay but it finally releases, thereby opening the ground connection to input terminal 25 of the transmitter T and releasing the transmitter to send in an alarm to the fire headquarters.

Operation of the premises station and subscriber's supervisory panel circuits in the fire alarm system in response to an open on the X line followed by a bona fide alarm

Referring again to Fig. 3 with the circuit in normal condition as shown, assume that from any cause the X line goes open somewhere between the supervisory panel SP and the subscriber's control box P. This stops the normal flow of current through the windings of relays 4, 2, 0, 1, 3, 8, and 7, and relays 1 and 8 thereupon immediately release.

The release of relay 8 connects the battery 18 in series with the winding of relay 7 from ground to both line conductors X and Y. No current can flow out over the X conductor, however, for the reason that that conductor is open. Neither can any current flow out over the Y conductor immediately for the reason that the release of relay 1 opened contacts F3 and T3 on that relay. However, the release of relay 1 completed a path from ground over contacts T1 and B1 of relay 0 and contacts B3 and T3 of relay 1 through the contacts B2 and T2 and the winding of relay 0 to contact T3 on relay 2.

Following the release of relays 1 and 8, slow-release relay 2 releases. This completes the path previously traced from ground up to contact T3 of relay 2 through contact B3 to conductor 11 of the loop circuit. At the same time conductor 11 is disconnected from the X line by the opening of contacts T1 and F1 on relay 2. The release of relay 2 also closes contacts T2 and B2 on that relay connecting the other loop conductor 12 to the line conductor Y. The final result is that the loop conductors 11 and 12, including the resistor 24, are left connected in series with the marginal relay 0 between ground at the premises station and the Y line conductor. Current flow is therefore resumed from battery at the supervisory panel SP through the relay 7 and through the winding of relay 3 out over the Y line conductor and, because of the fact that the slow release relay 2 is designed to release more quickly than the slow release relay 7, the latter is reenergized before it has opened its contacts F and T. It will be observed, therefore, that an open on the line conductor X does not release the alarm code transmitter T.

With the circuit rearranged as described in response to an open on X line, the total resistance in the circuit is reduced as a result of the elimination of relays 1, 2, 3 and 8, and line X. This might increase the current flow in the winding of the marginal relay 0 sufficiently to operate that relay. To prevent such operation, resistances 14 and 15 (referring for the moment to Fig. 2) are provided in series with the contact B1 on relay 0 and the contact B2 on relay 2, respectively, which relays are cut into the circuit in response to release of relays 1 and 2. The resistance 14 compensates for the resistance of relays 1, 3, 8 and the X line, and the resistance 15 compensates for the resistance of relay 2.

Now assume that a bona fide alarm is turned in, thereby short circuiting the loop conductors 11 and 12 and shunting out the resistance 24. This increases the current flow through the marginal relay 0 sufficiently to actuate that relay which locks up mechanically, as previously described. The operation of relay 0 breaks the contacts B1 and T1 on the latter relay, thereby opening the path to ground over which current previously flowed from the line conductor Y. The interruption of current flow over conductor Y permanently opens the circuit over which relay 7 was operated, thereby releasing that relay, which in turn releases relay 6 and opens the path from ground to the input terminal 25 of the transmitter T releasing the transmitter and sending in an alarm to the fire station.

Should line X, in addition to being opened, be grounded on the premises side of the break, it would not affect the foregoing operation since the release of relay 2 opens the premises end of X line at contacts T1 and F1 on relay 2.

Should line X, in addition to being opened, be grounded on the central station side of the break, then there would have been an increase of current flow from battery 18 through the winding of relay 4 to ground on the X line, which increased current flow would operate relay 4. When once operated, relay 4 locks up with the current supplied from battery over its contacts T3 and F3, through its winding and through its contacts T1 and F1 to ground. The operation of relay 4 opens the circuit to the X line at contacts B2 and T2, thereby preventing further flow of current through relay 7 to the ground on the X line. Thereafter the only current flowing

through winding of relay 1 is that which flows out over the Y line. When relay 4 operates, it completes a circuit from battery 18 through relay 1 over contacts T2 and F2 of relay 4 to contact T3 of relay 3, but under the conditions outlined relay 3 is not operated and therefore its contact T3 remains open.

10 *Operation of the premises station and subscriber's supervisory panel circuits in the fire alarm system in response to open on Y line followed by a bona fide alarm*

With the circuit in the condition shown in Fig. 3, assume that the Y line goes open. This opens 15 the circuit shown in heavy lines and stops the flow of current through relays 4, 2, 0, 1, 3, 8 and 1. Relays 1 and 8 release immediately, relay 1 opening the Y line at its contact F3 and grounding the loop conductor 12 through contacts F3 20 and T3 on relay 2, the winding of relay 0, contacts T2 and B2 of relay 0, contacts T3 and B3 of relay 1 and contacts B1 and T1 of relay 0; and relay 8 connecting battery 18 through its contacts T2 and B2, through the winding of relay 1, and 25 through contacts T1 and B1 of relay 8 to both line conductors X and Y through the relays 4 and 3, respectively. No current can flow out over the Y line because the latter is open. However, current can flow from battery 18 through the winding 30 of relay 1 and the winding of relay 4 out over the X line, through contacts T1 and F1, and the winding of relay 2, to the loop conductor 11 and thence through the loop resistor 24 to the loop conductor 12 and thence to ground over the 35 circuit previously traced. The resumption of current flow through relay 1 over the path traced prevents relay 1 from releasing so that the transmitter T is not released.

40 The circuit will now respond to a bona fide alarm in substantially the manner described in connection with an open on X line. Thus, a short on the loop conductors 11 and 12 shunts out the resistor 24, permitting an increase in the flow of current through the marginal relay 0 45 to actuate the latter, which breaks the path to grounds at contacts T1 and B1 on relay 0. This stops the flow of current from the battery 18 through the relay 1 and out over the X line, causing the relay 1 to release, which in turn releases relay 6 and breaks the path from ground to the terminal 25 of the transmitter, releasing the transmitter and sending in an alarm.

50 In case the Y line also becomes grounded on the premises side of the break, the circuit still 55 functions exactly as described up to the time the loop conductors 11 and 12 are short circuited in response to a bona fide alarm. Thereafter the operation is slightly different. Thus, when the relay 0 pulls in response to short circuiting 60 of the resistor 24, the current from X line through the relay 2 to ground is broken at contacts B2 and T2 and also at contacts T1 and B1 on relay 0, whereupon, after a slight delay, relay 2 releases. The release of relay 2 connects the loop conductor 65 12 through contacts T2 and B2 on relay 2 to the premises end of conductor Y which, if grounded as assumed, would supply an alternative path to ground independently of the normal path to ground through the contacts on relay 0. However, this makes no difference in the operation of 70 the circuit in response to an alarm for the reason that the release of relay 2 also opens contacts T1 and F1 on the latter, thereby opening the X line at the premises end and preventing any flow of 75 current through relay 1. The latter therefore

releases, as previously described, to actuate the transmitter T.

In case the Y conductor should be grounded on the central station side of the break, there would be an increased current flow through relay 3 immediately following the release of relay 8, to operate relay 3, which locks up over a local circuit the same as does relay 4, and open the Y line at the central station end at contact B4 on relay 3. At the same time flow of current from battery 18 through relay 1 and relay 3 is stopped by the opening of contacts T2 and B2 on relay 3.

10 *Operation of the premises station and subscriber's supervisory panel circuits in the fire alarm system in response to an open on the protection loop followed by a bona fide alarm*

15 With the circuit in the condition shown in Fig. 3, assume that either one of the loop conductors 11 or 12 is broken. This interrupts the normal 20 flow of current over the circuit shown in heavy lines, immediately releasing relays 1 and 8, as previously described. The release of relay 8 applies current from the battery 18 through the winding of relay 1 out over both line conductors 25 X and Y. No current can flow over the Y conductor, however, for the reason that it is opened at the premises end at contact F3 of relay 1 upon the release of that relay. Relay 1 in releasing, however, completes the circuit from ground over 30 contacts T1 and B1 of relay 0, contacts B3 and T3 of relay 1, through the contacts B2 and T2 and the winding of relay 0 over contacts T3 and F3 of relay 2 to the loop conductor 12. At the same time the release of relay 1 boxes the loop. 35 In other words, both ends of the loop conductor 12 are connected together over contacts B2 and T2 of relay 1 and both ends of the loop conductor 11 are connected together over the contacts B1 and T1 of relay 1. Therefore, a circuit 40 is established from the X line through the contacts T1 and F1 and the winding of relay 2 to the loop conductor 11 and a circuit is completed to the resistor 24, regardless of an open on conductor 11, through the boxing conductor and contacts B1 and T1 of relay 1. Likewise the circuit 45 is continued from resistor 24 to the ground connection previously described, regardless of an open circuit condition on loop conductor 12, through the boxing conductor and contacts B1 50 and T1 of relay 1. If the loop conductors 11 and 12 are now short circuited by one of the danger responsive devices 13, the resistor 24 is short circuited and the current through the marginal relay 0 increased to operate that relay as previously described, and the operation of relay 0 55 breaks the path to ground at the premises station, thereby stopping the flow of current through relay 1, releasing the latter, which in turn releases relay 6 and actuates the transmitter T.

60 *Operation of the premises station and subscriber's supervisory panel circuits in the fire alarm system in response to a short on the line conductors followed by a bona fide alarm*

65 With the circuit in the condition shown in Fig. 3, a short across the line conductors X and Y shunts out the relays 1 and 2 and relay 1 immediately releases to connect the alarm loop and winding of relay 0 in series between the line conductor X and ground in the manner previously 70 described.

75 At the same time the short circuit on line conductors X and Y permits an increased current to flow through the relays 3 and 4 connected in

series with the **X** and **Y** lines, respectively. Relay 3 is adjusted to operate before relay 4 and under most conditions will be the only one of the two relays to operate in response to a short on the line conductors **X** and **Y**. The operation of relay 3 immediately opens the **Y** line at contact B4 on relay 3 and also breaks the heavy-line circuit including relay 8 at contact B2 on relay 3. Relay 8 thereupon immediately releases and in doing so connects the relay 7 in series with the battery 18 through relay 4 to the **X** line over the circuit previously traced. Current thereafter flows from battery 18 through relay 7 and relay 4 out over the **X** line through the relay 2, the loop and the marginal relay 0 to ground over the contacts T3 and B3 of relay 1. The fact that **X** and **Y** lines are short circuited produces no effect for the reason that the **Y** line is now open at each end. The occurrence of a bona fide alarm shunting out the resistor 24 increases the current flow through relay 0 to operate the latter and break the ground connection at the premises station, as previously described. This stops the flow of current out over the **X** line and releases relays 7 and 6 to actuate the transmitter T.

Should for any reason both relays 4 and 3 operate in response to a short on the line conductors **X** and **Y**, the circuit still functions as described except for the following difference: The operation of relay 4 opens the **X** line at contact B1 on relay 4 and also opens the path from battery through relay 1 at contact B2 on relay 4. However, when relay 4 operates a circuit is completed over contacts T2 and F2 on relay 4 to contact T3 on relay 3, and operation of relay 3 completes this circuit from contact T3 over contact F3 back to the **X** line so that a circuit is restored from the winding of relay 1 to **X** line. A bona fide alarm thereafter causes the release of relay 1 exactly as outlined above.

*Operation of the premises station and subscriber's supervisory panel circuits in the fire alarm system in response to a ground on the **Y** line followed by a bona fide alarm*

With the circuit in normal condition, as shown in Fig. 3, a ground on the **Y** line shunts out relay 8 causing the latter to release. As relay 8 releases, the normal circuit from battery 18 out through relay 4 and over the **X** line is momentarily interrupted at contacts T2 and F2 on relay 8, causing the release of relay 1 at the premises station. Following this momentary break, however, the relay 8 reestablishes a circuit from battery 18 through relay 7 to both the **X** and **Y** lines, as previously explained. The release of relay 1 at the premises station establishes a circuit from **X** line through the loop and resistor 24 and thence through the relay 0 to ground, as previously explained. At the same time the release of relay 1 disconnected the **Y** line from the premises circuit at contact F3 on relay 1.

The establishing of a circuit from battery 18 through relay 7 and relay 3 to the **Y** line permits a heavy flow of current through relay 3 to the **Y** line and thence to ground. This operates relay 3 and the latter in operating opens the **Y** line at the central station end at contact B4 on relay 3 and also breaks connection from relay 3 to relay 7 at contact B2 on relay 3. Thereafter normal current flow continues from battery 18 through relay 7 and relay 4 out over **X** line through relay 2, the loop circuit, and the marginal relay 0 to ground, and if the resistance 24 is shunted out in response to a bona fide fire

alarm the current through relay 0 is increased to operate the latter relay and break the ground connection, as previously described, thereby releasing relay 7 and actuating the transmitter T.

*Operation of the premises station and subscriber's supervisory panel circuits in the fire alarm system in response to a ground on the **X** line followed by a bona fide alarm*

With the circuit in the condition shown in Fig. 3, a ground on the **X** line shunts out relays 2, 1, 8 and 7, causing relays 1 and 8 to immediately release. Relay 8 in releasing reestablishes the circuit from battery 18 through relay 7, through both relays 3 and 4 to the line conductors **X** and **Y**. The release of relay 1 opens the **Y** line at contact F3 on relay 1 and establishes a ground connection through contacts T1 and B1 of relay 0, contacts T3 and B3 of relay 1, contacts B2 and T2 and the winding of relay 0, to contact T3 of relay 2. Relay 2 thereafter releases, completing the circuit from its contact T3 over contact B3 to the loop conductor 11, at the same time completing a circuit from loop conductor 12 over contacts T2 and B2 of relay 2 to line conductor Y.

Following release of relay 8, excessive current flowed from battery 18 through relay 7 and relay 4 to line **X** and thence to the ground on that line. This operated relay 4 which locked up in the manner previously described and opened the **X** line at contact B1, and opened the circuit from relay 7 at contact B2.

The net result of the foregoing operations in response to a ground on **X** line is that normal battery feed is reestablished through relay 7 and relay 3 out over **Y** line, thence over contacts B2 and T2 on relay 2 to loop conductor 12, thence through resistor 24 and loop conductor 11 through contacts B3 and T3 on relay 2, through the winding of relay 0 to ground. Thereafter shunting out of the resistor 24 in response to an alarm operates the relay 0 to break the ground connection and interrupt the current flow through relay 7 to release the transmitter T.

Operation of the premises station and subscriber's supervisory panel circuits in the fire alarm system in response to ground on the loop conductor 11 followed by a bona fide alarm

With the circuit in normal condition as shown in Fig. 3, assume that the outside loop conductor 11 becomes grounded. This shunts out the relays 1, 8 and 7, immediately releasing relays 1 and 8. The release of relay 8 reestablishes the circuit from battery 18 through relay 7 and through relays 4 and 3 to line conductors **X** and **Y**. No current flow can occur over the **Y** conductor, however, because the latter is opened at contact F3 on relay 1 at the premises end. However, the ground on the outside loop conductor 11 permits an abnormal current flow through relay 4, causing that relay to operate and lock up in the manner previously described. In operating, relay 4 opens the **X** line at contact B1 on relay 4 and also completes a circuit from relay 7 over contacts T2 and F2 on relay 4 to contact T3 on relay 3.

Following the interruption of current flow over the **X** line by relay 4, relay 2 releases, disconnecting the outside loop conductor 11 from the **X** line and connecting it through contacts B3 and T3 on relay 2 through the winding and contacts T2 and B2 of relay 0, through contacts T3 and 75

B3 on relay 1 and contacts B1 and T1 on relay 0 to ground. The release of relay 2 also connects the loop conductor 12 through back contacts T2 and B2 of relay 2 to the Y line conductor.

This establishes a circuit for normal current flow from battery 18 through relay 7 and relay 3 out over the Y line conductor to loop conductor 12, thence through the resistor 24 to the loop conductor 11 and thence to ground over the trouble ground on loop conductor 11. There is also a path to ground, previously traced, from loop conductor 11 through the relay 0 but unless the trouble ground is of considerable resistance, little or no current will flow through relay 0 in response to shunting of the resistor 24.

Shunting of the resistor 24 in response to a bona fide alarm permits an increased current flow through relay 3 out over line conductor Y, to loop conductor 12, thence to loop conductor 11 and to ground. This increased current flow actuates relay 3, which locks up in the manner previously described and breaks the Y conductor at contact B4 of relay 3 and breaks the circuit from relay 7 to relay 3 at contact B2 on relay 3. This stops flow of current through relay 7, releasing the latter to actuate the transmitter T.

It will be observed that there is another path for current from the battery 18 through relay 7 over the contacts T2 and F2 of relay 4, and the contacts T3 and F3 of relay 3 to the line conductor X. However, there can be no current flow to hold up relay 7 out over this path for the reason that the line conductor X has been opened at the central station end at contact B1 on relay 4 and at the premises end on contact T1 of relay 2.

Operation of the premises station and subscriber's supervisory panel circuits in the fire alarm system in response to a ground on the loop conductor 12 followed by a bona fide alarm

With the circuit in normal condition as shown in Fig. 3, assume that a ground occurs on the inside loop conductor 12. This shunts out the relays 1, 3, 7, and 8 and relays 1 and 8 immediately release. The release of relay 8 reestablishes connection from battery 18 through relay 7 and through the relays 3 and 4 in parallel to the line conductors X and Y. No current flow can occur over the Y conductor for the reason that the line is opened at contact F3 on relay 3 at the premises end. Normal current flow, however, is restored through the relay 4, line conductor X, through the contacts T1 and F1 and winding of relay 2 to the loop conductor 11, through the resistor 24 to the loop conductor 12 and thence to ground over the trouble ground thereon. This condition obtains until resistance 24 is shunted out in response to a bona fide alarm. Shunting out of the resistor 24 increases the current flow through marginal relay 4 sufficiently to actuate the latter relay, which locks up as previously described and opens the line conductor X at contact B1 on relay 4. This stops the flow of current over line X, causing relay 2 to release. The release of relay 2 establishes a connection from line Y over contacts B2 and T2 of relay 2 directly to the loop conductor 12 which is grounded. This immediately produces a heavy current flow through relay 3, operating the latter and locking it up. The operation of relay 3 breaks the flow of current through relay 7 to the Y line at contact B2 on relay 3, causing relay 7 to release and actuate the transmitter T.

There is also a path for current through relay

7 over contacts T2 and F2 of relay 4, thence over contacts T3 and F3 of relay 3 to the line conductor X but no current flow can occur over this path for the reason that the X line is opened at the central station end at contact B1 on relay 4 and is opened at the premises end at contact T1 on relay 2.

Alternative premises circuit for fire alarm system

A modification of the premises circuit shown in Fig. 3 is disclosed in Fig. 4, in which elements corresponding to those in Fig. 3 bear the same reference numerals with the suffix "a".

It will be observed that the circuit of Fig. 4 is substantially the same as that of the premises circuit in Fig. 3 except for the arrangement and connections of the contacts on relays 1a and 2a, respectively. Thus in Fig. 4, while the contacts for boxing the loop conductor 12a are on the relay 1a, as in Fig. 3, the contacts for boxing the loop conductor 11a are on relay 2a. This alteration in the boxing circuits permits the connection of the coil of marginal relay 0a directly to the loop conductor 12a instead of connection through the contacts T3 and F3 of relay 2, as shown in Fig. 3.

The circuit shown in Fig. 4 gives the same final result under each of the conditions of operation outlined hereinbefore, except in response to a ground on the loop conductor 11, as the premises circuit shown in Fig. 3. Thus relay 1a immediately releases in response to interruption of current therethrough to connect the relay 0a in series between ground and the loop conductor 12a and to open the connection between the Y conductor and the winding of relay 0a. Relay 0a functions in response to an increase in current flow therethrough above normal value to break the path to ground and open the connection from the loop conductor 12a, through the winding of relay 0a, to the contact T3 of relay 1a. Relay 2a functions in response to prolonged interruption of current therethrough to open the line conductor X at the premises end, connect the line conductor Y to the loop conductor 11a and box the loop conductor 11a.

Thus with the line conductors X and Y in normal condition, the shorting of one of the thermostatic elements 13 causes relay 0a to pull and lock up, thereby breaking all connection to ground at the premises end of the line regardless of the positions of relays 1a and 2a, and permanently stopping flow of current through relay 7 to release the latter, which in turn releases relay 6 and opens the ground connection to the transmitter T causing the latter to transmit an alarm.

In response to an open on the Y line, relays 1a and 8 release as previously described, connecting the battery 18 through relay 7 out over the X line through the contacts T1 and F1 and winding of relay 2a to the loop conductor 11a, through the resistance 24a, through the winding and contacts T2 and B2 of relay 0a, through the contacts T3 and B3 of relay 1a and contacts B1 and T1 of relay 0a to ground. Thereafter shorting of one of the thermostatic elements 13a causes relay 0a to pull and lock up, permanently breaking the path to ground at contact B1 on relay 0a and causing the release of relays 1 and 6 and the actuation of transmitter T, as previously described.

In response to an open on the X line, relays 1 and 8 release and thereafter relay 2 releases exactly as described in connection with Figure 3,

the circuit being reconvereted to connect battery 18 through relay 7 out over the Y line and through the contacts B2 and T2 on relay 2a to loop conductor 11a, the other loop conductors 12a being connected to ground through the winding and contacts of relay 0a and the contacts T3 and B3 of relay 1a. Shorting of one of the elements 13a thereafter actuates the relay 0a to break the connection to ground and actuate the transmitter T at the central station in the manner previously described.

In response to an open on the loop conductor 12a, relays 1a and 8 release. Relay 1a in releasing boxes the loop conductor 12a over its contacts B2 and T2 and completes a circuit from ground through contacts T1 and B1 of relay 0a, contacts B3 and T3 of relay 1a, contacts T2 and B2 of relay 0a and the winding of relay 0a to the loop conductor 12a. At the same time the release of relay 8 has applied battery through relay 7 out over the X line through the contacts T1 and F1 and the winding of relay 2a to the loop conductor 11a. The system is therefore restored for transmission of an alarm. Shorting the circuit of the loop conductors 11a and 12a in response to actuation of one of the alarm responsive devices 13a thereafter causes relay 0a to pull and lock up in the manner previously described to break all connections to ground and cause the release of relays 7 and 6 and the actuation of the transmitter T.

In response to an open on the loop conductor 11a, the circuit of Fig. 4 functions as follows: Relays 1 and 8 immediately release, as previously described, the release of relay 1a completing the path to ground through relay 0a to the loop conductor 12a. However, since the loop conductor 11a is open, current feed from the X line to relay 2a is cut off and the latter relay releases, thereby opening the X conductor at contact T1 on relay 2a, boxing the conductor loop 11a over the contacts T3 and B3 on relay 2a and also connecting the boxed loop conductor 11a through contacts T2 and B2 on relay 2a to the Y line conductor. Thereafter current is supplied from the battery 18 on the central station through relay 7 out over the Y line to loop conductor 11a and thence through the resistance 24a, through the loop conductor 12a and the relay 0a to ground. Short circuiting of the loop conductors 11a and 12a in response to an alarm thereafter causes relay 0a to pull and lock up, permanently opening the path to ground and causing the release of relays 7 and 6 and the actuation of the transmitter T at the central station.

In response to a short on the line conductors X and Y, the operation of the circuit of Fig. 4a is substantially the same as that of the circuit of Fig. 3. Relay 1a first releases, connecting the loop conductor 12a through the winding or relay 0a to ground. Thereafter relay 3 at the central station operates, opening the Y line conductor and causing the release of relay 8, which upon releasing applies battery through relay 7 and relay 4 out over line conductor X through the contacts T1 and F1 and the winding of relay 2a to the loop conductor 11a. Thereafter shorting of the loop conductors in response to an alarm pulls and locks up the relay 0a to break the path to ground and cause the release of relays 7 and 6 and the actuation of transmitter T at the central station.

The operation of the circuit of Fig. 4 in response to a ground on Y line is also substantially the same as in the case of Fig. 3. Relay

8 releases, connecting the battery 18 directly through relay 7 and through relays 3 and 4 to both the X and Y line conductors. At the same time the momentary opening of the normal circuit by relay 8 before the application by that relay of current to both line conductors X and Y releases the relay 1a. Thereafter heavy flow of current through the relay 3 to the ground on the Y conductor pulls relay 3, opening the Y line. This leaves the circuit with current flowing from battery 18 through relay 7 out over the X line, through the contacts T1 and F1 and the winding of relay 2a, through the loop conductors and resistance 24a and the winding of relay 0a to ground. Thereafter short circuiting of the loop resistance 24a in response to an alarm causes relay 0a to pull and open the path to ground, releasing relays 7 and 6 and actuating the transmitter T at the central station.

In response to a ground on the X line, the circuit of Fig. 4 also functions substantially the same as that of Fig. 3. Thus, relay 1a and relay 4 pull, opening the X line at the central station end and releasing relay 8. After a short interval relay 2a releases. Thereafter current flows from battery 18 through relay 7 out through relay 3 over the Y conductor, through the contacts B2 and T2 of relay 2a to the loop conductor 11a, thence through the resistance 24a to a loop conductor 12a and through the relay 0a to ground. Short circuiting of the loop resistor 24a in response to an alarm thereafter causes the relay 0a to operate and open the path to ground, which in turn causes the release of the relays 7 and 6 and the actuation of the transmitter T at the central station.

In response to a ground on the loop conductor 12a, the circuit of Fig. 4 functions as follows: Relays 1a and 8 release, completing a circuit for current from battery 18 through relay 7, relay 4, line conductor X, the contacts T1 and F1 and winding of relay 2a to the loop conductor 11a and thence through the resistor 24a to the ground on the loop conductor 12a. Thereafter short circuiting of the resistor 24a in response to an alarm increases the current through relay 4, causing the latter to pull and open the X line at the central station end. Since the Y line conductor was previously opened at contact F3 on relay 1a, no current can flow at this time out over the Y conductor from the central station. However, following the opening of the X conductor by the relay 4, relay 2a releases which connects the Y conductor to the loop conductor 11a, through contacts T2 and B2 on relay 2a. This permits a heavy flow of current through relay 3, causing the latter to pull and open the Y conductor at the central station end. With relays 3 and 4 both pulled, a circuit is completed from the battery 18 through relay 7, the contacts T2 and F2 of relay 4, and the contacts T3 and F3 of relay 3 to the X line conductor. However, there can be no flow of current out over the X line at this time because the latter is opened at the premises end at contact T1 on relay 2a. Therefore, all paths to ground from relay 7 are broken and the latter releases, causing the release of relay 6 and the actuation of the transmitter T.

In response to a ground on the loop conductor 11a, the circuit of Fig. 4 transmits a fire alarm instead of reconverting the circuit into operative condition to receive a bona fide alarm. Thus in response to a ground on the loop conductor 11a relays 1 and 8 release, completing a circuit for

current from battery 18 through relay 1, relay 4, the X line conductors, contacts T1 and F1 and the winding of relay 2a to ground on the loop conductor 11a. This causes a heavy flow of current through relay 4 which operates to open the X line. Thereafter relay 2a releases, connecting the grounded loop conductor 11a over contacts B2 and T2 on relay 2a to the Y line conductor. This results in a heavy flow of current through relay 3 at the central station, causing the latter to operate and open the Y line conductor but at the same time completes another circuit from battery 18 through relay 1, contacts T1 and B1 of relay 8, contacts T2 and F2 of relay 4, contacts T3 and F3 of relay 3, to the X line conductor. However, the X line conductor is now open at the premises end at contact T1 on relay 2a. Therefore, all paths to ground are opened and the relays 1 and 6 release, causing the actuation of the transmitter T.

It will be observed from the foregoing description that the circuit of Fig. 3 is superior to that shown in Fig. 4 in that it will respond to a ground on the outside loop conductor 11 to release the circuit for reception of a bona fide alarm without actually sending in an alarm at the time the ground occurs.

Effect on the fire alarm system of an open on both line conductors or a ground on both line conductors

If both line conductors X and Y (Fig. 3) are opened or grounded, the line is totally incapacitated for any signaling between the premises and central stations.

An open on both line conductors sends in a fire alarm since it first causes the release of relay 8 and thereafter the release of relays 1 and 6. It will be observed that relay 7 must release because when the circuit has been converted by the release of relay 8 there can be no path for current from battery 18, through relay 1 without a ground somewhere on the system. This ground can be provided only at the premises station and with both line conductors X and Y open there is no connection to the premises station.

A ground on both line conductors X and Y does not automatically send in a fire alarm. Thus, in response to a ground on both line conductors X and Y, relay 4 pulls causing the release of relay 8. Thereafter relay 3 pulls. With both relays 3 and 4 operated, a path is completed from battery 18 through relay 1 over contacts T1 and B1 of relay 8, contacts T2 and F2 of relay 4, contacts T3 and F3 of relay 3 to the X line and thence to ground, and current flow over this circuit maintains relay 1 operated. It is to be understood that in an actual system an operator is always on duty at the central station who will immediately be acquainted, in a manner to be described, of trouble conditions on the line so that following the grounding of both line conductors X and Y this operator would immediately take steps to insure the protection of the premises associated with the grounded line until the line has been repaired.

Circuit for indicating the existence of line faults in the fire alarm system

It will have been observed from the foregoing description of the operation of the fire alarm system shown schematically in Fig. 3 that either a short on the line conductors X and Y, an open on either or both line conductors X or Y, a ground on either or both line conductors X or Y,

an open on either or both loop conductors 11 or 12, or a ground on either or both loop conductors 11 or 12, caused the release of relay 8 at the central station. It is apparent, therefore, that relay 8 releases in response to any of the line or loop faults enumerated and that this relay may therefore be employed to give an indication at the central office of the existence of any of the enumerated faults.

Referring now to Fig. 2, it will be observed that relay 8 is provided with an extra armature contact T6 and cooperating front contact F6 (these contacts not being shown in the schematic circuit of Fig. 3). It will be observed that when relay 8 is operated, which condition obtains only when the entire circuit is in normal condition, a circuit is completed from ground over contacts F6 and T5 of relay 8, through the winding of the trouble alarm relay 10 and thence back to battery 18. Therefore, when the system is in normal condition relay 10 is actuated and maintains its associated contacts in open condition. However, when relay 8 releases in response either to any line trouble or to a fire alarm, relay 10 is released by the opening of contacts F6 and T6 on relay 8. Thereupon relay 10 releases, completing a circuit from ground over its contacts T2 and B2, through a buzzer cutout key 21, and a buzzer 20 to the battery 19 and completes another circuit from ground over contacts T1 and B1 on relay 10 through the blue lamp B to battery 19. Therefore, as soon as any trouble arises in the system or a bona fide fire alarm is sent in, the buzzer 20 sounds and the blue lamp B lights. The buzzer 20 may be silenced by manually opening the buzzer cutout key 21 but the blue lamp B continues lighted until relay 8 is restored to normal position.

To enable the attendant at the central station to ascertain whether the blue lamp B has been lighted in response to line faults or a bona fide alarm, the red lamp R is provided. This lamp is connectible between the battery 19 and ground through the back contact B and armature T of relay 6. It will have been observed from the description of operation in response to a fire alarm that the transmitter T is never released to transmit an alarm until relay 6 releases. Therefore, the red lamp R is never lighted unless the transmitter T has been released to transmit an alarm. Accordingly, if lamp B only is lighted, the attendant knows that a trouble condition has arisen on the line or loop circuit whereas if both lamps B and R are lighted the attendant knows that an alarm has been sent in.

Restoration of the premises station and subscriber's supervisory panel circuits to normal condition following an alarm or trouble condition

Following the existence of line trouble and/or the transmission of a bona fide alarm, some or all of relays 1, and 2 at the premises station and relays 6, 7, 8 and 10 on the subscriber's supervisory panel SP are released and some or all of relays 1 at the premises station and relays 3 and 4 on the subscriber's supervisory panel may be locked up. It is to restore these relays to normal condition (the condition shown in Fig. 2) that key A on the subscriber's supervisory panel and key Z at the premises are provided. The resetting or restoring operation is performed as follows:

The handle A1 on key A on the subscriber's supervisory panel is first moved to the right.

This disconnects the battery A from the feed circuit to transfer contact T2 on relay 8 at contacts B2 and T2 on key A and connects the battery feed through contacts T2 and F2 on key A 5 to contact B1 on relay 8. Contacts T3 and F3 on key A connect the white lamp W in series between the battery 19 and ground, causing this lamp to light and remain lighted as long as the handle A1 on key A is actuated to the right. 10 Key A is preferably designed to remain locked in the right position until released and the white lamp W serves as a constant indicator to the operator that this key is out of its normal position. Contacts B4 and T4 on key A are in series 15 with the contact T1 on relay 8 and serve to break the connection between the X line and relay 1 which was closed at the time relay 8 released in response to a trouble or alarm condition in the circuit. Contacts B7 and T7 on key A are connected in series between the contact T8 on relay 8 and the contact B2 on relay 3, over which connection was made in response to release of relay 8 between the Y line and relay 1. Contacts T7 20 and F7 on key A are bridged across contacts F4 and T4 on relay 8 and serve to reestablish connection between the winding of relay 8 and the Y line. Contacts T8 and F8 on key A are bridged across contacts F5 and T5 on relay 8 and serve to reestablish normal connection between the 25 winding of relay 1 and ground. Contacts T9 and F9 on key A serve to apply ground to the winding of relay 6 to restore that relay.

It will be observed from the foregoing that movement of handle A1 on key A to the right 30 directly restores relay 6; reconnects the battery 18 to contact T2 on relay 4 (and through contact B2, the winding of contacts T1 and B1 of relay 4 if the latter is released to the X line conductor); reconnects the relay 8 and the relay 1 in series 35 between ground and the contact B2 on relay 3 (and thence through contact T1, the winding of contacts T4 and B4 of relay 3 and contacts T5 and B5 and key A to the Y line if relay 3 is not 40 operated); and lights the signal lamp W.

In the meantime an attendant has been sent 45 to the premise's station and following the movement of key A and the subscriber's supervisory circuit at the central station to the right as described, this attendant actuates the key Z at 50 the premise's station and releases the latch 17 on the relay 0 if the latter has been operated. Actuation of key Z closes contacts F1 and T1 on that key, which bridge the contacts F1 and T1 55 on relay 2, thereby reestablishing connection between the X line to the loop conductor 11 through the winding of relay 2. At the same time actuation of key Z closes contacts T2 and B2 thereon to bridge the contacts F3 and T3 on relay 1 and reconnect the Y line through the winding of relay 60 1 and the contacts B2 and T2 and the winding of relay 0 to contact T3 on relay 2. Actuation of key Z also opens the normally closed path from contact B3 on relay 1 to ground over contacts T3 and B3 of key Z. It will be observed, 65 therefore, that actuation of key Z completes a circuit from line conductor X through the winding of relay 2 to loop conductor 11, thence through the loop resistor 24 to the loop conductor 12, and thence through contacts T2 and B2 on 70 relay 2, and the resistor 15 to the Y line conductor. Now if relays 3 and 4 at the central station were not operated, the movement of key A to the 75 line conductor X to battery and line conductor Y to ground at the central sta-

tion. However, to restore relays 3 and 4 to normal unoperated condition in case one or both of them happens to be operated, the central station attendant next moves the handle A2 on key A momentarily to the left. This opens the 5 battery feed through resistance 22 to the locking contacts of relays 3 and 4 at contacts T1 and B1 on key A to release those relays.

With relays 3 and 4 released, current from the battery 18 flows out over X line, through the contacts T1 and F1 on key Z, through the winding of relay 2, through the loop conductor 11, loop resistor 24, loop conductor 12, contacts T2 and B2 of relay 2, through resistor 15, to line conductor Y and thence to ground at the central 10 station. This energizes relay 2, which when it pulls up completes a circuit from line conductor X, contacts T1 and F1 and winding of relay 2, 15 loop conductor 11, loop resistor 24, loop conductor 12, contacts F3 and T3 on relay 2, the 20 winding of contacts T2 and B2 of relay 0, contacts B2 and T2 of key Z, the winding of relay 1, back to the Y line conductor, causing relay 1 to pull and complete its holding circuit through its 25 own contacts F3 and T3.

It will be observed that following the foregoing operations all the relays in the system have been restored to normal condition. The operator at the central station thereafter restores the key A to normal position by moving the handle A1 to 30 the left, which reestablishes the subscriber's supervisory panel circuit to the normal condition shown in Fig. 3. Thereafter the attendant at the premises station restores key Z to normal 35 position, leaving the premises circuit in the normal condition shown in the schematic circuit of Fig. 3. Restoration of key A at the central station extinguishes the white lamp W. If the line and loop circuits are in normal condition, the relays 6, 7 and 8 will remain operated and the 40 red and blue lamps R and B, respectively, will likewise be extinguished. These three signal lamps W, R and B, therefore, inform the operator that the entire circuit is in normal condition 45 awaiting an alarm.

The apparatus at subscriber's premises and on the subscriber's supervisory panel in the burglar alarm system

As previously mentioned, my burglar alarm 50 system differs from my fire alarm system only in the apparatus at the subscriber's premises and on the subscriber's supervisory panel SP at the central office, the transmitters T (referring for the moment to Fig. 1), line finders LF, headquarters' lines supervisory panels HP, headquarters' line HL and alarm recorders AR being identical in both fire and burglar alarm systems. The burglar alarm circuit for the apparatus at the subscriber's premises P and on the subscriber's 55 supervisory panel SP is shown in detail in Fig. 5 and schematically in Figs. 6 and 7.

Referring first to Fig. 6, circuit elements in the burglar alarm system corresponding in function 60 to those in the fire alarm system are indicated by the same reference numerals with the prime mark added. Thus it will be observed that relays 1' and 2' in Fig. 6 correspond to relays 1 and 2 at the premises station in Fig. 3 but that there 65 is no relay at the premises station in the burglar alarm system corresponding to relay 0 in the fire alarm system. Relays 3', 4', 6', 7' and 8' on the subscriber's supervisory panel in the burglar 70 alarm system correspond in function to relays 75

3, 4, 6, 7 and 8 in the fire alarm system. However, the subscriber's supervisory panel equipment in the burglar alarm system includes an additional relay 5 not present in the fire alarm system.

The protection loop at the premises station in the burglar alarm system (Fig. 6) includes a pair of loop conductors 11' and 12', respectively, interconnected by a resistor 24' but the alarm responsive devices 13' in the burglar alarm system are adapted to open the loop circuit in response to danger instead of shorting the loop circuit as was the case in the fire alarm system. It will be observed that whereas in the fire alarm system the loop circuit was indirectly opened by the relay 0 in response to a short on the loop caused by a danger condition, the loop in the burglar alarm system is directly opened in response to danger without the use of a relay.

20 A full operation of the burglar alarm system disclosed in Figs. 6 and 7 will now be explained with reference to various line faults and alarm conditions that may arise. It will be shown that the system illustrated in Figs. 6 and 7 will respond to release the transmitter T and transmit an alarm to police headquarters in response to any one of the following conditions:

- (1) An open in any part of the loop circuit;
- (2) A ground on the loop conductor 11';
- (3) A short across the loop conductors 11' and 12';
- (4) An open on both line conductors X' and Y';
- (5) A ground on both line conductors X' and Y';

35 and that the system will give a trouble indication and restore the line and loop circuits into condition to transmit a bona fide alarm following:

- (1) A short circuit on the line conductors X' and Y';
- (2) An open on either line conductor X' or Y';
- (3) A ground on either line conductor X' or Y';
- 45 and that it will respond to a resistance bridge maliciously placed across line conductors X' and Y' followed by an open circuit in the protection loop.

50 *Normal operation of the premises station and subscriber's supervisory panel circuits in the burglar alarm system in response to a bona fide alarm*

Referring to the schematic diagram of Fig. 6, which shows the premises and subscriber's supervisory panel circuits in normal condition awaiting an alarm, assume that a burglar attempts to break into the premises and thereby actuates one of the danger-responsive devices 13' to open the loop circuit. This opening of the loop circuit 55 stops the flow of current from the central station over the circuit shown in heavy lines. Thus this circuit may be traced from grounded battery 18' through the winding of relay 5', over contacts T2 and F2 of relay 8', the contacts B2 and T2, the winding, and contacts B1 and T1 of relay 4', out over the line conductor X' through the winding, and contacts F1 and T1 of relay 2' through the loop conductor 11', the loop resistor 24', the 60 loop conductor 12', contacts F3 and T3, winding of relay 1', back over the line conductor Y', through contacts B3 and T4, the winding, and contacts T2 and B2 of relay 3' through the contacts F4 and T4, to the winding of relay 8', 65 through the winding of relay 7' and thence

70 through contacts F5 and T5 on relay 8' back to ground. As in the fire alarm system described in connection with Fig. 3, the loop resistor 24' is of such value, relative to the potential of battery 18' and the characteristics of the various relays 75 in the heavy line circuit that under normal conditions relays 1', 2', 7' and 8' are operated (the condition shown in Fig. 6). This normal current flow, however, is insufficient to operate relays 3', 4' and 5. So long as the relay 7' is operated, it 10 completes a circuit from ground over contacts T and F of relay 1' through the winding of relay 6', thence through the contacts B and T of relay 5 to battery 18', thereby maintaining relay 6' operated, and as long as relay 6' is operated, 15 it connects ground to the input terminal 25' of the transmitter T. The other input terminal 26' of transmitter T is permanently connected to the battery, as shown. As was previously stated in connection with the fire alarm system, the 20 transmitter T remains locked up as long as the input terminal 25' is connected to ground and is released to transmit an alarm responsive to opening of the contacts F and T on relay 6'.

With the loop circuit open, in response to an 25 attempted burglary, as previously stated, the heavy line circuit is opened causing the immediate release of relays 1' and 8'. The release of relay 1' disconnects the loop conductor 12' from the line conductor Y' over contacts T3 and F3 30 on relay 1' and at the same time reconnects loop conductor 12' to ground over contacts T3 and B3 of relay 1' through a reactance element 32 (this reactance element has a low resistance for direct current but a high impedance for alternating 35 current for a purpose to be described later).

The release of relay 8' reconverts the circuit on the supervisory panel to apply battery directly through relay 7 to both line conductors X' and Y' in substantially the same manner as was 40 described in connection with the fire alarm circuit of Fig. 3. Thus following the release of relay 8' the circuit may be traced over battery 18' through the winding of relay 5 over contacts T2 and B2 of relay 8' through the winding of relay 7', thence through contacts T1 to contact B1 on 45 relay 8'. From contact B1 a circuit is completed as previously traced over contacts T2 and B2, the winding, and contacts B1 and T1 of relay 4' to the line conductor X'. At the same time a circuit is 50 completed from contact B1 on relay 8' to the line conductor Y' which may be traced from contact B1 over contacts B3 and T3 on relay 8', thence over contacts B2 and T2, the winding, and contacts B4 and T4 of relay 3'.

55 The application of battery to line conductor Y' produces no immediate flow of current there-through because the latter is open at the premises end at contact F3 on relay 1' and contact B2 on relay 2'. However, an appreciable interval after the opening of the loop circuit in response to an attempted entry of the premises, the slow-release relay 2' releases. This opens the line conductor X' at contact F1 on relay 2' to connect the loop conductor 11' through contacts T1 and B2 on 60 relay 2' to the line conductor Y'. Despite this circuit conversion at the premises station, no current flow can occur over either line conductor because of the fact that the loop circuit is open. Therefore, after an additional interval of time 65 following the release of relay 2', relay 7' releases, causing the release after a further interval of time, of the slow-release relay 6' which releases the transmitter T to send in the alarm.

Operation of the premises station and subscriber's supervisory panel circuit in the burglar alarm system in response to a ground on the loop conductor 11'

- 5 The system will also respond to transmit an alarm in response to a ground on the loop conductor 11', which ground might readily result from an attempt on the part of an intruder to tamper with the alarm circuit. The system responds to a ground on the loop conductor 11' as follows:
- 10 The ground on the loop conductor 11' shunts out both relays 1' and 8', causing their immediate release. The relay 1' in releasing transfers the loop conductor 12' from connection to the Y' line conductor to ground, the release of relay 8' reapplies battery through relay 7' to both line conductors through relays 3' and 4'. The ground on the loop conductor 11' causes a current in excess of normal value to flow out over the line conductor X', which current pulls relay 4' (this relay locking up over its contacts F3 and T3 and T1 and F1 exactly as described in connection with the fire alarm system of Fig. 1). The operation of relay 4' opens the line conductor X' at contacts B1 on relay 4' thereby stopping flow of current through relay 2' at the premises station, which releases after an interval. The release of relay 2' disconnects the loop conductor 11' from the line conductor X' and connects loop conductor 11' to line conductor Y'. Thereafter a heavy current flows out through the Y' line to the ground on the loop conductor 11' pulling relay 3' which locks up in exactly the manner described in connection with the fire alarm system. With both relays 3' and 4' pulled, the line conductor Y' is permanently opened at contacts B4 on relay 3'. However the circuit from battery 18' through the winding of relay 5, the various back contacts on relay 8', and the winding of relay 1' is recompleted to line conductor X' through contacts T2 and F2 on relay 4', contacts T3 and F3 on relay 3'. No current, however, can flow out over the line conductor X' because the latter is open at the premise's end at contact F1 on relay 2'. Therefore all current flow through relay 1' is stopped and relays 7' and 6' release after an interval of time to release the transmitter T.

Operation of the premises station and subscriber's supervisory panel circuit in the burglar alarm system in response to a short on the loop conductors

- 55 The system shown in Fig. 6 responds to a short circuit across the loop conductors 11' and 12' (which may be occasioned by tampering with the circuit), to transmit an alarm as follows:
- 60 Assuming the circuit in the condition shown in Fig. 6, a short across the loop conductors 11' and 12' shunts out the loop resistor 24', thereby causing an increase in the flow of current over the heavy line circuit sufficient to actuate relays 3' and 4'. As in the fire alarm system, however, relay 3' is adjusted to pull before relay 4' and ordinarily will be the only one to pull immediately in response to the shunting of the loop resistor 24'. The operation of relay 3' opens the line conductor Y' at contact B4 on relay 3', immediately releasing relays 1' and 8'. Relay 1' immediately transfers the loop conductor 12' from connection to the line conductor Y' to connection to ground through the reactance element 32. The release of relay 8' immediately re-

establishes current flow from battery 18 through the winding of relays 5, 7' and 4' out over the line conductor X' through relays 2' to loop conductor 11', thence through the short across the loop conductors to ground. This causes relay 5 to pull which opens the circuit from relay 7' to the line conductor X' over the contacts B1 and T1 of relay 4' but reestablishes a circuit to the line conductor X' over contacts T2 and F2 of relay 4', and contacts T3 and F3 of relay 3'. Therefore, a current in excess of normal value continues to flow through the windings of relays 5 and 7'. Relay 5 is a marginal relay adapted to pull on this excessive current flow and when pulled it opens its contacts T and B to break the current supply for the winding of relay 6' with the result that after a short interval of time the relay 6' releases to release the transmitter T and transmit an alarm.

Operation of the premises station and subscriber's supervisory panel circuits in the burglar alarm system in response to an open or ground on both line conductors

An open circuit condition of both line conductors X' and Y' completely incapacitates the line for indication or signaling purposes, and the system is therefore arranged to transmit an alarm to police headquarters in response to such a condition. The system functions in this respect as follows:

Opening of the line conductors X' and Y' immediately releases relay 8'. The latter, in releasing, re-establishes a circuit from battery through relays 5 and 7' to both line conductors. However, the latter being open, no current flow can occur and after an interval of time the slow-release relays 7' and 6' release, thereby releasing the transmitter T to transmit an alarm code to the police headquarters.

Since a ground on both line conductors X' and Y' also totally incapacitates the line for signaling purposes, the system is adapted to transmit an alarm code to police headquarters in response to occurrence of such a condition.

With the circuit in the normal condition as shown in Fig. 6, the ground on either of the line conductors X' or Y' shunts out the relay 8' causing the latter to release and re-establish connection from battery 18 through the windings of relays 5 and 7' to both line conductors. Thereafter the excessive current flow to both line conductors through relays 3' and 4' causes both of those relays to pull. As has been previously explained, with both relays 3' and 4' operated a circuit is completed through contacts T2 and F2 on relay 4' and contacts T3 and F3 on relay 3' to the line conductor X'. Thereafter following the operation of relays 3' and 4' a heavy flow of current still persists through relays 5 and 7' to the ground on the line conductor X'. This excessive current flow actuates the marginal relay 5 to open the operating circuit of relay 6' thereby releasing that relay which in turn releases the transmitter T.

Operation of the premises station and subscriber's supervisory panel circuits in the burglar alarm system in response to a short on the line conductors X' and Y' followed by an abnormal condition in the loop circuit

A short on the line conductors X' and Y' does not incapacitate the line for signaling purposes. The system is, therefore, designed to convert this

line to maintain the system in condition to respond to a bona fide alarm without actually sending in an alarm at the time trouble occurs.

With the system in the normal condition as shown in Fig. 6, a short across the line conductors X' and Y' immediately causes an increased current flow from battery $18'$ through relays 5 and $4'$ to the line conductor X' , thence through the short and through line conductor Y' back through the relays $3'$, $3'$ and $1'$ to ground. Relay $3'$ immediately pulls, opening the line conductor Y' and momentarily opening the energizing circuit for relay $8'$ causing the latter to release. The release of relay $8'$ reconnects the battery $18'$ through relays 5 , $7'$ and $4'$ to the line conductor X' . The short across the line conductors X' and Y' also shunted out the relays $1'$ and $2'$ at the premises station end and relay $1'$ immediately released to transfer the loop conductor $12'$ from connection to the line conductor Y' to connection to ground. However, before the slow-release relay $2'$ had time to release, potential was restored to the line conductor X' by the disconnection of the line conductor Y' at the central station end, at contact $B4$ of relay $3'$. The momentary increase of current flow to relay 5 might also have pulled that relay (although relay 5 is adjusted to operate on a heavier flow of current than relay $3'$) to open the operating circuit of relay $6'$; however, relay 5 was again released in response to the opening of the line conductor Y' by relay $3'$ before relay $6'$ had time to release.

As a result of the foregoing operations, the system is restored to alarm-responsive condition by completion of a circuit for normal current flow from battery $18'$ through relay 5 , relay $7'$, relay $4'$ through line conductor X' , the relay $2'$, loop conductor $11'$, loop resistor $24'$ and loop conductor $12'$ to ground. If the loop circuit is now opened in response to a bona fide alarm by actuation of one of the elements $13'$, the normal flow of current is interrupted, causing the release of relay $1'$, which in turn releases relay $6'$ which in turn releases the transmitter T to send an alarm. Relay $2'$ also releases in response to the open loop condition but this does not prevent the release of relay $1'$ because, regardless of whether the line conductor X' or Y' is connected to the loop conductor $11'$, there can be no current flow as the path to ground from the loop conductors $11'$ has been opened.

The system (as converted after a short on the line conductors X' and Y') will also respond to a short on loop conductors $12'$ and $13'$, shorting out the resistor $24'$. This causes relay $4'$ to pull but the only effect is to reestablish the connection from relay $1'$ to the line conductor X' over contacts $F2$ and $T2$ of relay $4'$ and contacts $T3$ and $F3$ of relay $3'$ instead of through contacts $T2$ and $B2$, the winding and contacts $B1$ and $T1$ of relay $4'$. The increased current flow, therefore, continues and actuates the marginal relay 5 for a sufficient length of time to cause the release of relay $6'$ and the release of the transmitter T .

The system will also respond to a ground on the loop conductor $11'$ to transmit an alarm. It will be unnecessary to trace the whole sequence of operations under these conditions, as they are identical with the sequence of operations in response to a short on the loop conductors which was outlined in the preceding paragraph.

Operation of the premises station and subscriber's supervisory panel circuits in the burglar alarm system in response to an open on the line conductor X' followed by an abnormal condition in the loop circuit

5

With the circuit in normal condition, as shown in Fig. 6, an open on the line conductor X' interrupts the normal flow of current over the path shown in heavy lines, immediately releasing relays $1'$ and $8'$. The release of relay $1'$ transfers the loop conductor $12'$ from connection to the line conductor Y' to connection to ground and the release of relay $8'$ reconnects the battery $18'$ in series with the relays 5 and $7'$ to both line conductors. No current can flow out over the line conductor X' , however, because the latter is open. Likewise at the moment no current can flow out over the line conductor Y' because the latter is open at the premises end at contact $F3$ on relay $1'$ and contact $B2$ on relay $2'$. However, since the open circuit condition on line conductor X' also interrupted the flow of current through relay $2'$ the latter releases after a short interval and in releasing disconnects loop conductor $11'$ from the line conductor X' and connects it to the line conductor Y' through contacts $T2$ and $B2$ of relay $2'$. Thereafter normal current flows from battery $18'$ through relays 5 and $7'$ and $3'$ out over the line conductor Y' through contacts $T2$ and $B2$ of relay $2'$ to the loop conductor $11'$ and thence through the loop resistor $24'$ and loop conductor $12'$ to ground.

15

20

25

30

35

With the circuit in the condition last described an open in the loop conductor releases the relay $7'$ by cutting off the path to ground therefrom, causing the release of relay $6'$ and the release of transmitter T .

The system will also respond to a short on the loop or a ground on the loop conductor $11'$ (following an open on the line conductor X') to transmit an alarm as follows:

Either a short on the loop conductors $11'$ or $12'$ or a ground on the loop conductor $11'$ shunts out the resistor $24'$, thereby permitting an increased current flow through relay $3'$ causing the latter to pull thereby opening connection between relay $1'$ and line conductor Y' at contact $B2$ on relay $3'$ causing relays $7'$ and $6'$ to release and release the transmitter T to transmit an alarm.

Operation of the premises station and subscriber's supervisory panel circuits in the burglar alarm system in response to an open on the line conductor Y' followed by an abnormal condition in the loop circuit

55

With the circuit in normal condition as shown in Fig. 6, an open on the line conductor Y' immediately releases relays $1'$ and $8'$ as described in connection with an open on the line conductor X' , the relay $1'$ transferring the loop conductor $12'$ from connection to the line conductor Y' to ground and the relay $8'$ applying battery $18'$ through relays 5 and $7'$ and through relays $3'$ and $4'$ to both line conductors. The line conductor Y' being open, no current flow can occur thereover. However, normal current flow is re-established through relay $4'$ and line conductor X' , the winding, and contacts $F1$ and $T1$ of relay $2'$ through the loop conductors and loop resistor to ground.

60

65

70

75

Thereafter an open on the loop circuit breaks the path to ground stopping the flow of cur-

rent through relay 1' and causing the latter to release and release relay 6' which in turn releases the transmitter T. The system also functions to transmit an alarm in response to a short 5 on the loop conductor or a ground on the loop conductor 11' since either condition shunts out the resistor 24' thereby increasing the current flow through relay 4' and causing the latter to operate. The operation of relay 4' breaks the 10 current flow from relay 1' to the line conductor X' causing the relay 1' to release and release relay 6' which in turn releases the transmitter T.

15 *Operation of the premises station and subscriber's supervisory panel circuits in the burglar alarm system in response to a ground on the line conductor X' followed by an abnormal condition in the loop circuit*

20 With the circuit in normal condition as shown in Fig. 6, a ground on the line conductor X' immediately shunts out relays 1' and 8' causing them to release. Relay 1' transfers the loop conductors 12' from connection to the line conductor Y' to ground. Release of relay 8' reconnects the relays 5 and 7' in series between the battery 18' and both line conductors X' and Y' through relays 4' and 3', respectively. Thereafter heavy flow of current occurs through relay 30 4' to ground on line conductor X' opening the latter at contact B' on relay 4'. After a slight interval slow-release relay 2' also releases, transferring loop conductor 11' from connection with the line conductor X' to connection with the line conductor Y'. This reestablishes a circuit for normal current flow from battery 18' through relays 5, 7' and 3', thence out over the line conductor Y' and through contacts B2 and T2 on relay 2' to the loop conductor 11' and thence 35 through the loop resistor 24' and the loop conductor 12' to ground. With the circuit in the condition last described, an open in the loop circuit stops the flow of current through the relay 7' causing the release of the latter and the release of relay 6' to release the transmitter T.

40 A short circuit on the loop conductors 11' and 12' causes an increased current flow through relay 3' which thereupon pulls and reconnects the relay 7' to the line conductor X' over contacts T2 and F2 on relay 4' and contacts T3 and F3 on relay 3'. Since the line conductor X' is grounded, an increased current thereafter flows through relays 5 and 7' causing relay 5 to pull and release the relay 6' which, in turn, releases the 45 transmitter T to transmit an alarm.

50 Since a ground on the loop conductors 11' has the same direct effect as a short across the loop conductors 12' and 13', it likewise actuates the circuit to release the transmitter T in the manner 55 just described.

60 *Operation of the premises station and subscriber's supervisory panel circuits in the burglar alarm system, in response to a ground on the line conductor Y', followed by an abnormal condition in the loop circuit*

65 With the circuit in normal condition as shown in Fig. 6, a ground on the line conductor Y' shunts out the relay 8' causing the latter to release and 70 re-establish current supply through relays 5 and 7' to both line conductors X' and Y'. In releasing, relay 8' momentarily interrupts the current supplied to line X', causing the release of relay 1' at the premises station, which transfers the 75 loop conductor 12' from connection to the line

conductor Y' to connection with ground. Following the release of the relay 8' an excessive current flow occurs through the relays 5 and 7' and 3' to the ground on line conductor Y', causing relay 3' to pull and open the Y' line conductor at contact B4 on relay 3'. Thereafter normal current flow continues from battery 18' through relays 5, 7' and 4' out over the line conductor X' through the relay 2' and its contacts F1 and T1, thence through the loop conductor 11', loop resistor 24' and loop conductor 12' to ground. 10

15 With the circuit in the condition last described an open in the loop circuit causes actuation of one of the devices 13', opens the path to ground for the current flow through relays 5 and 7', and causes the release of relay 1', the release of relay 6', and the release of the transmitter T to transmit an alarm.

20 If, instead of an open circuit occurring in the loop, the loop conductors 11' and 12' become 25 shorted, or the loop conductor 11' becomes grounded, the resistor 24' is shunted out increasing the current flow sufficient to pull the relay 4'. This produces no change in the circuit, however, since relay 3' was previously operated, and with 25 both relays 3' and 4' operated, the circuit is re-established from relay 1' to the line conductor X'. Therefore the excessive current flow continues and pulls the relay 5 to release the relay 6' and release the transmitter T to transmit an 30 alarm.

35 *Operation of premises station and subscriber's supervisory panel circuits in the burglar alarm system in response to a ground on the loop conductor 12', followed by another abnormal condition in the loop circuit*

40 The system shown in Fig. 6 will respond to a ground on the loop conductor 12' to release relay 8' at the central station and thereby give a 40 trouble indication, but will not transmit an alarm. Thus a ground on the loop conductor 12' shunts out relays 1' and 8' and causes their immediate release. The release of relay 1' breaks connection between the loop conductor 12' and the line 45 conductor Y' and reinforces the ground on loop conductor 12'. Following the release of relay 8' a circuit is re-established from battery 18 through relay 5 and relay 7' out over the line conductor X' through the winding of relay 2' to 50 loop conductor 11', and thence through the resistor 24' to ground on the loop conductor 12'. The resistor 24' still being in circuit, the current flow is insufficient to actuate relay 4' and the circuit will remain in the condition outlined ready 55 to respond to an open circuit on the loop should one occur in response to a bona fide alarm. Should an open on the loop circuit occur the transmitter T will be released to transmit an alarm substantially as described in connection 60 with the normal operation of the system.

65 *Operation of the premises station and subscriber's supervisory panel circuits in the burglar alarm system, in response to a resistance bridge across the line conductors X' and Y', followed by an abnormal condition in the loop circuit*

70 In most instances, the only trouble or fault conditions that can occur on the line conductors X' and Y', are those previously enumerated, 70 namely, a short on the line, or a ground, or an open on either or both lines. However, skilled criminals might attempt to disable the circuit shown in Fig. 6 by shunting a resistance across the line conductors X' and Y' of such value as to 75

carry enough current to maintain relay 8' operated without increasing the current flow sufficiently to operate relays 3', 4' or 5. If this were done, the criminal could thereafter open the line circuit on the premises side of the bridge without sending in an alarm. To prevent the possibility of the system being disabled in this manner, the premises circuit of Fig. 6 may be modified as shown in Fig. 7 by replacing the loop resistor 24' 10 with a slow-release relay 28 having contacts T and B shunted across the winding and contact T3 of relay 1'. The winding of the relay 28 has the same resistance as the resistor 24' for which it is substituted so that it functions to limit the 15 normal current flow in the system to a value insufficient to actuate the relays 3', 4', 7' and 5. This normal current flow through the winding of relay 28, however, is sufficient to maintain it operated under which condition the contacts T and B thereon are open.

Relay 28 is designed to release (following interruption of current flow therethrough) even more slowly than the slow-release relays 2', 7' and 6' so that it does not interfere with the normal operation of the system under the various conditions specified hereinbefore.

Now with the circuit of Fig. 6, modified as shown in Fig. 7, in normal condition, assume that a resistance bridge is shunted across the line conductors X' and Y' of sufficiently low resistance to maintain the relays 7' and 8' operated independently of flow of any current through the premises circuit, but of not low enough resistance to increase the current 35 flow to a value sufficient to operate the relays 3', 4' and 5. Assume next that the criminal enters the premises and in doing so actuates one of the danger-responsive devices 13' and opens the loop. This interrupts the flow of current through relays 40 1' and 2', relay 1' releasing instantly and relay 2' releasing after a short interval. Up to this point, however, nothing has happened in the supervisory panel circuit for the reason that relay 8' is still held up by normal current flow through the resistance bridge across the line conductors X' and Y'. The opening of the loop circuit, however, de-energizes the relay 28 and after a prolonged interval of time this relay releases to close its contacts T and B and connect the line conductor Y' 45 to the loop conductor 12' which has previously been connected to ground over the contacts T3 and B3 of relay 1' when the latter released. This applies ground to the line conductor Y' and shunts the normal current flow away from relay 8' 50 causing the latter to release and reconnect the battery 18 through relays 5 and 7' to both line conductors. Insufficient current flow can occur through relay 4' to operate it for the reason that the only path to ground from the line conductor X' is through the resistance bridge. However, a heavy flow of current occurs through the 55 relays 5 and 3' to the line conductor Y', causing relays 5 and 3' to operate. The operation of relay 3' opens the line conductor Y' at contact B4 on relay 3', thereby interrupting the heavy initial flow of current through relay 5. However, there is still a flow of current through relays 5 and 7' to the line conductor X', thence through the resistance bridge across the line conductors to line conductor Y' and thence through the contacts of relay 28 and the contacts T3 and B3 of relay 1' to ground. It was previously stated that this flow of current was insufficient to operate relay 60 5. However, after relay 5 has once been pulled

by the initial heavy flow of current through relay 3' to the line conductor Y', relay 5 will hold up on the current flowing to the line conductor X', thereby opening the contacts T and B on relay 5 for a prolonged interval of time to release relay 6' which in turn releases the transmitter T to transmit an alarm.

Line fault indicating equipment on the subscriber's supervisory panel in the burglar alarm system 10

The equipment and circuits for indicating the existence of trouble on the line or loop circuit in the burglar alarm system are substantially the same as in the fire alarm system. Thus in each 15 system the relay 8 or 8' releases in response to a trouble condition, and auxiliary contacts T6 and F6 on this relay are opened in response to release of the relay 8 or 8' to release the trouble alarm relay 10 or 10' in the respective circuits. 20 The release of the relay 10' in the burglar alarm system (Fig. 5) closes circuits for the operation of the alarm buzzer 20' and the blue lamp B' exactly the same as the corresponding elements were operated in the fire alarm system of Fig. 2. 25

Likewise the release of the relay 6' in the burglar alarm circuit of Fig. 5 to release the code transmitter T also completes a circuit to energize the red lamp R' and visually indicate that an alarm has been transmitted. 30

Restoration of premises and subscriber's panel apparatus in the burglar alarm system to normal condition following a trouble condition or the transmission of an alarm 35

The burglar alarm system shown in detail in Fig. 5 includes on the subscriber's supervisory panel SP a key A' corresponding in function to the key A in the fire alarm system previously described. The circuit connections to this key 40 need not be described in detail since they correspond to those in the fire alarm system.

The apparatus for restoring the relays at the premises station, however, is quite different from that in the fire alarm system since in the burglar alarm system I provide special means for resetting the premises relays from the central station by means of a key 30 and a key 33. The complete operation of resetting is as follows:

First handle A2 on key A' is moved to the left 50 to release relays 3' and 4' in case they were locked up. Then the handle A'1 on key A' is moved to the right and left in that position to operate relay 6' and relay 8'. Next the handle 301 of key 30 is moved to the right to close contacts T5 and F5 thereon and place a shunt around the marginal relay 5 to prevent it from operating and releasing relay 6'. (The remaining circuit operations performed by the manipulation of key 30 are of no interest in connection with the resetting operation but are useful for a different purpose to be described later). Thereafter the handle 302 on key 30 is moved to the right closing contacts T8 and F8 to shunt out relay 3' and prevent its operation and to close contacts T9 and F9, shunting relay 4' to prevent its operation; thereafter while handle 302 is held to the right the key 33 is actuated first to the right and then to the left or vice versa to successively apply alternating current from a source 34 to the two line conductors X' and Y'. Alternating current applied to the line conductor X' flows out to the premises station, through the winding of relay 2', through a condenser 35 bridging the contacts T1 and F1 70 75

5 of relay 2', thence through the contacts T1 and B1 and the contacts T2 and B2 of a key 29 to the loop conductor 11', through the loop resistor 24', back through the loop conductor 12', through contacts B3 and T3 and contacts B4 and T4 of key 29, through an A. C. bell 36 and a condenser 37 to ground. This alternating current is preferably 10 of low frequency and is sufficient to pull the relay 2', which relay when once pulled immediately locks up over its contacts T1 and F1 with direct 15 current supplied over the line conductors X' and Y' from the battery 18 at the central station. Likewise the alternating current impulses applied to the line conductor Y' flow out to the premises station, through the winding of relay 1', through 20 a condenser 38 to contact T2 of key 29, from which point the current continues to ground over the same path traced for alternating current applied to the line conductor X'. This alternating current in the winding of relay 1' pulls that relay 25 which thereafter locks up with the normal direct current flow from the central station. The reactance element 32 is connected in series in the path to ground from contact B3 on relay 1' to prevent the alternating current from being bypassed to ground at that point.

Following the manipulation of key 33 to apply the alternating current to the line conductors X' and Y' for resetting the premises relays 1' 30 and 2', the handles 30₂ and 30₁ of key 30 are restored to normal position, removing the shunts from relays 3', 4' and 5, and thereafter the key A' is restored to normal position, leaving all the 35 relays in the condition shown in Fig. 5.

35 *Equipment in the burglar alarm system and the operation thereof for switching the premises loop from day to night condition*

Although the loop conductors 11' and 12' in 40 Fig. 5 may comprise single continuous conductors, as shown and described in connection with the schematic diagram of Fig. 6, it is advantageous to separate the loop circuit into two sections, one section including those protective devices on a premises which should be maintained in alarm responsive condition at all times, and the other section including danger responsive means such as door switches on doors which are normally opened and closed frequently during 45 the daytime but which are supposed to be maintained closed at night. In accordance with the detail circuit of Fig. 5, I provide a system whereby that portion of the loop circuit incorporating door switches and other devices which are not 50 used during the daytime are included in a separate loop section adapted to be shunted out during the daytime. Thus in Fig. 5 that portion of loop conductor 11' extending from point 39 to point 40 is adapted to be shunted out by actuation of the key 29 and likewise that portion of loop conductor 12' between points 41 and 42 is adapted to be shunted out by movement of the key 29. The remaining portion of the loop included between points 40 and 42 (including the 55 loop resistor 24') is always connected in the circuit regardless of the position of key 29 and this portion of the loop circuit will include protective devices on windows, bank vaults, or other portions of the building which are to be protected 60 by the burglar alarm system at all times. On the other hand, the danger responsive devices associated with doors in the protected building, which are frequently opened during business hours and upon which burglar protection is not desired during 65 certain hours of the day, are included in the

section of the loop between points 39 and 40, and 70 41 and 42, respectively. As previously indicated, the day loop (as that section of the loop between points 39 and 40, and 41 and 42, respectively, will hereinafter be termed) is connected into or out of the protection circuit by manipulating key 29. 75 However, key 29 is designed to be operated in a certain relation with respect to key 30 at the central station and a full understanding of the functions of the various contacts on these keys, 10 together with certain auxiliary apparatus at the central station, can best be explained by following through the routine operation of the circuit.

Let it be assumed that the circuit is in condition for night operation (the condition shown 15 in Fig. 5) with both the day and night loops in use and that at a certain hour in the morning, say at 8 o'clock, the day loop is to be disconnected. A short time before 8 o'clock the attendant at the central office will throw the handle 30₁ on 20 key 30 to the right and leave it there. This movement opens or closes the various contacts associated with handle 30₁ to perform the following functions: Contacts T1 and F1 are closed 25 to complete a path to ground from the white signal lamp W', lighting that lamp (it will be remembered that the white lamp W' is also lighted when the handle A' of key A' is moved to the right so that this lamp when lighted always indicates to the operator that either key 30 or key A' is out of normal position). Contacts B2 and T2 are opened, thereby cutting the winding of a premises door signal relay 9 into the line conductor X' ahead of the relay 4'. Contacts 30 T3 and F3 close to complete a circuit from buzzer 20' up to contact T1 on relay 9. (Contact T1 on relay 9 is open at this time because relay 9 was operated by the normal current flow out over the line conductor X' immediately upon its connection into the circuit.) Contacts T4 and F4 on key 30 are closed to complete a circuit from battery 19' up to the premises door signal lamp 31 associated with the relay 9. Contacts T5 and F5 on key 30 are closed to place a shunt around the relay 5 and prevent the latter from operating 45 to release the alarm relay 6'. Contacts T6 and F6 are closed to place a shunt across contacts F5 and T5 on relay 8' to prevent opening of the path between ground and the winding of relay 7' in case relay 8' should release. Contacts T7 and F7 are closed to bridge a resistor 43 across the line conductors X' and Y' on the supervisory panel circuit side of relays 3' and 4' to hold 50 relay 8' up.

55 It will be observed that as a result of the foregoing operations accomplished by moving handle 30₁ of key 30 to the right that the relays 5', 6', 7', 8', 3', and 4' are prevented from operating to transmit an alarm and that the relay 9 has been connected in series with the line conductor X' and is operated by the normal current flow out over the line. At the same time circuits have been prepared for the operation of the buzzer 20' and the lighting of the signal lamp 31 in response to release of the relay 9.

With the circuit prepared as described, at the usual time of 8 o'clock an attendant or a watchman at the premises manipulates the key 29 thereat. Key 29 is preferably a lock switch so 70 arranged that when the key is inserted and turned it first momentarily opens contacts T1 and B1 and then shifts the handle member 29₂ into right hand position and thereafter again closes contacts T1 and B1. 75

Since the contacts T₁ and B₁ on switch 29 are connected directly in series with the line conductor X', through windings and contacts F₁ and T₁ of relay 2', opening of these contacts T₁ and B₁ on switch 29 interrupts the flow of current in the line and in the loop, causing the release of relays 1' and 2' in a manner previously described. Thereafter the movement of the switch member 29₂ to the right cuts out the day loop by the opening of contacts B₂ and T₂, and B₃ and T₃ and reconnects the remaining portion of the loop in circuit through contacts T₂ and F₂ and T₃ and F₃. At the same time contacts B₄ and T₄ are opened to disconnect the alarm bell 36 from the switch contact T₃ and connect the latter through contact F₄ through a condenser 44 to ground.

The opening of the contacts T₁ and B₁ of switch 29 not only released the relays 1' and 2' on the premises station but also interrupted the flow of current out over the line conductor X', thereby releasing the relay 9 at the central station. The release of this relay completed a circuit over its contacts T₂ and B₂ to light the signal lamp 31 and another circuit over its contacts T₁ and B₁ to actuate the buzzer 20'. This indicates to the attendant at the central station that the switch 29 has been actuated, at the premises station to cut out the day loop. Thereupon he shifts handle 30₂ on switch 30 to the right to shunt out the relays 3' and 4' and actuates the switch 33, while holding handle 30₂ depressed, to apply alternating current successively to the two line conductors X' and Y'. Thereafter the attendant restores the key 30 to normal position, which in turn restores the entire circuit to normal condition.

When alternating current was applied to the line conductor X' it flowed through the winding of relay 2', resetting the latter, thence through the condenser 35, through contacts T₁ and B₁ of switch 29, through contacts T₂ and F₂ of switch 29, out to point 40, through the loop conductor 24, back to point 42, thence over contacts F₃ and T₃ and contacts T₄ and F₄ of switch 29, through condenser 44 to ground. With the switch handle 29₂ in the right hand position, the A. C. bell 36 is disconnected and the attendant at the premises is acquainted by the fact that the bell does not ring that he has properly actuated the switch 29 into day position. The relay 1' is also reset by the alternating current applied to the line conductor Y' over the following circuit: from line conductor Y' through the winding of relay 1', through condenser 38, contacts T₂ and F₂ of switch 29, through the loop conductors and resistor 24', over contacts F₃ and T₃ and contacts T₄ and F₄ of switch 29 to ground through condenser 44.

The routine at the central station and at the premises station in rearranging the loop circuit for night operation is exactly the same except that this time the attendant at the premises releases the switch member 29₂ back into the normal position shown in Fig. 5. Following this operation, when the operator at the central station manipulates the key 33 and thereby applies alternating current to the line conductors X' and Y', the alternating current after passing through the relays 1' and 2', instead of going to ground over contact F₄ on switch 29 through condenser 44, goes to ground over contact B₄ on switch 29 and thence through the A. C. bell 36 and the condenser 37 to ground. This causes the bell 36 to

ring as the operator at the central station resets the relays 1' and 2', giving the attendant at the premises station an audible signal that he has properly manipulated the switch 29 into condition for night operation, and that all of the safety devices in the loop circuit are in normal condition.

Construction and operation of the alarm code transmitter T in both the fire and burglar alarm systems

Although various forms of automatic code transmitters may be employed in connection with the subscriber's supervisory panel circuits described, a particularly desirable transmitter is shown schematically in Fig. 8.

Referring to Fig. 8, the transmitter therein depicted comprises a spring motor 50 connected in driving relation by means of a shaft 51 directly to a cam 52 and through a pair of gears 53 and 54 to a shaft 55 upon which is mounted a code-transmitting cam 56. The shaft 55 is also coupled through gears 57 and 58 and gears 59 and 60 to a shaft 61 having a projecting member 62 secured thereto. A stop pawl 63 on a bellcrank lever 64 is adapted to engage the end of the lever 62 and lock the motor 50 in response to energization of a relay 65 having an armature 66 adapted to engage with one end of the bellcrank lever 64. The armature 66 also actuates a switch 67 to close the contacts T₁ and F₁ and open contacts T₂ and B₂ when the armature 66 is attracted. The switch 67 is also adapted to be operated independently of the armature 66 by a lever 68 fulcrumed at point 69 and pivotally connected at its outer end to a bellcrank lever 70 fulcrumed at point 71. The lever 70 has attached thereto an armature 72 adapted to be attracted by an electromagnet 73. The lever 70 is provided with a beveled end 74 adapted to be engaged under certain conditions of operation by a latch rod 75 pivotally secured at one end to the armature 66. Lever 70 is also pivotally connected adjacent the end 74 to a bar 76 which extends upwardly to a point adjacent the cam 52 and this upper end of bar 76 cooperates under certain conditions of operation with a projection 77 on cam 52. The bar 76 is also pivotally connected by a link 78 to one end of a bellcrank lever 79 fulcrumed at point 80, the other end 81 of which bellcrank is adapted under certain conditions of operation to be moved into the path of the projection 62 on shaft 61.

The cam 52 is also provided with a projecting pin 82 adapted to engage with a contact 83 during a portion of its movement and move that contact out of engagement with a cooperating contact 84. Cooperating with the cam face of cam 52 is a cam follower 85 which controls a pair of contacts 86 and 87, respectively.

The functioning of the transmitter elements described will now be explained by following through the operation of the device: In the drawings the parts are shown in full lines in their normal positions under which conditions the spring motor 50 is wound but is prevented from rotating by engagement of the projection 62 with the stop pawl 63 on bellcrank lever 64 which is maintained in the position shown by the armature 66 of relay 65. Relay 65 is normally energized from the battery 18 through the contacts T and F of relay 6 on the supervisory panel as previously described, this circuit being completed from the input terminals 25 and 26 on the trans-

mitter to the winding of relay 65 through the contacts T1 and F1 on switch 67. The transmitter remains in the waiting position shown until the relay 6 on the subscriber's supervisory panel of the fire alarm system or relay 6' on the subscriber's supervisory panel of the burglar alarm system, is released to open its contacts T and F, thereby breaking the energized circuit of relay 65 in the transmitter and causing the latter to release its armature 66. The armature 66 when released falls back into the position shown in dotted lines, at the same time dropping the stop pawl 63 and permitting the spring motor 53 to rotate the cam 52, the code transmitting cam 56 and the projection 62. The ratio between the gears 53 and 54 is such that the code transmitting cam 56 makes five revolutions while the cam 52 is completing one revolution, and cam 56 immediately begins actuating its associated coding contacts 56B and 56T which are connected in series between the output terminals 88 and 89 of the transmitter through contacts 83 and 84 associated with the pin 82 on cam 52 and the contacts B2 and T2 on switch 67. Thus it will be observed that contacts T2 and B2 on switch 67 are connected between output terminal 89 and the coding contact 56B and the contacts 83 and 84 are connected between the output terminal 88 and the coding contact 56T. Switch 67 was released in response to the release of relay 65, thereby closing contacts B2 and T2 on switch 67 to complete the circuit from the output terminal 89 to coding contact 56B and the circuit from the other output terminal 88 to coding contact 56T. Switch 67 was already completed because contacts 83 and 84 are normally closed. However, during the initial revolution of the coding cam 56 the circuit to the output terminals 88 and 89 is not interrupted because the coding contacts are shunted by contacts 86 and 87 which are closed because the cam follower 85 is on the low portion of the cam surface on cam 52. This delay in the transmission of coding impulses to the output terminals 88 and 89 and thence to the line finder LF is to give the line finder time to find a line.

This line finder LF has been indicated merely in the drawings as a device having a pair of input terminals connected directly to the output terminals 88 and 89 of the transmitter and having a plurality of sets of contacts, each set connected to one of the headquarters line supervisory panels HP. Thus in Fig. 9 the line finder LF is shown as having one set of three contacts, 90, 91 and 92, connected to one headquarters line supervisory panel HP and having other similar sets of contacts adapted to be connected to the other two headquarters line supervisory panels shown in the general layout diagram of Fig. 1. The line finder LF is of standard construction, such as has been used for years in automatic telephony and for that reason its construction has not been shown in detail.

The disclosure of a standard line finder construction adaptable for use in my circuit may be found on pages 25, 26, 57, 58, and 59 of "Automatic Telephone Practice", fourth edition, published and sold by Harry E. Hershey, 1017 Highland Avenue, Oak Park, Illinois.

Suffice it to say that the line finder in addition to the contacts connected to the various headquarters line supervisory panels includes a set of three brushes 93, 94 and 95, respectively, adapted to be automatically moved into connection with the various contacts connected to the headquarters line supervisory panels. The contacts

91 and 92 and brushes 94 and 95 are in the line circuits, respectively, of the line finder of the headquarters line supervisory panels HP. The contact 90, associated with each headquarters line supervisory panel is the supervisory contact 5 associated with that line conductor and functions to indicate to the corresponding brush 93 in the line finder whether or not that line is in condition to be seized. Thus if the contact 90 is connected to ground in the headquarters line supervisory panel, the line finder LF will not seize that line but will move its brushes 93, 94 and 95 successively over the contacts associated with the different headquarters line supervisory panels until it finds an idle line having no ground on its 15 supervisory contact 90.

The line finder is normally inactive but is energized to hunt for and connect its brushes 93, 94 and 95 to the contacts associated with an idle headquarters line in response to completion of a 20 circuit across its input terminals. As previously stated, such a circuit was completed in the transmitter T in response to the release of relay 65, through contacts B2 and T2 on switch 67, the contacts 86 and 87 associated with the cam follower 25 85, and the contacts 83 and 84 back to the other input terminal of the line finder. Therefore, immediately following the release of the transmitter, and ordinarily during the time that the coding and transmitting cam 56 is completing 30 its first revolution, the line finder LF seized the contacts 90, 91 and 92 associated with an idle headquarters line as shown in Fig. 9. Upon seizing the contacts 91 and 92, the line finder also completes a circuit from its input terminals 35 (which are connected directly to the output terminals 88 and 89 on the transmitter) directly to the brushes 94 and 95, thereby connecting the transmitter output terminals directly to the line contacts 91 and 92 of the headquarters line supervisory panels HP. This headquarters line supervisory panel HP includes a coding relay 96 which has a pair of windings 97 and 98, respectively. Winding 97 is connected directly in series between the contact 91 and the ungrounded terminal of a 40 grounded battery 99. The other winding 98 is connected directly in series between the line contact 92 and ground. Therefore, following seizure of the contacts 91 and 92 by the line finder, current is supplied from battery 99 through the winding 97 of coding relay 96 over contact 91 and brush 94 in the line finder to output terminal 88 of the transmitter, thence through the transmitter circuit and back to the output terminal 89, thence through the line finder over brush 95 45 and contact 92 back through windings 98 on coding relay 96 to ground, and following the first revolution of the coding cam 56, the shunt is removed from the coding contacts 56B and 56T by the opening of contacts 86 and 87, by cam follower 50 85, so that the coding contacts 56B and 56T open and close the energized windings 97 and 98 of relay 96 causing the latter to close and open its associated contacts T2 and B2 to relay the alarm code to the alarm recorder at police or fire headquarters. The specific circuits extending from the contacts of coding relay 96 to the alarm recorder will be described later.

The coding cam 56 will make four complete 70 revolutions following the removal of the shunt across the coding contacts 56B and 56T by the opening of contacts 86 and 87 associated with cam 52 during which time, of course, the cam 52 is completing one revolution. At the end of this 75

revolution the mechanism is stopped, by means of the relay 73, and associated mechanism, in the following manner:

It will be observed that the winding of relay 73 is connected in shunt to the contacts 83 and 84, which contacts are normally closed, so that no appreciable current can flow through the winding of relay 73. However shortly before the cam 52 completes its revolution the pin 32 thereon engages with the contact 73 and carries it out of contact with contact 84, thereby removing the shunt from the winding of relay 73. Thereupon current flows from the battery 99 in the headquarters line supervisory panels HP (Fig. 9) to output terminal 88 of the transmitter, thence through the winding of relay 73, through the contacts 86 and 87 associated with the cam follower 85 (which contacts are now closed because the cam follower 85 is on the lower portion of the cam face), and thence through contacts T2 and B2 on switch 67 back to output terminal 87 on the transmitter and thence to ground in the headquarters supervisory panel and relay 73 is thereupon energized and attracts armature 72 and lifts lever 70 into the position shown in dotted lines in Fig. 8. This movement of lever 70 also shifts the lever 68 into the dotted line position, thereby actuating the switch 67 into the position shown, in which position its contacts B2 and T2 are open 30 and contacts T1 and F1 are closed.

It will be observed that the opening of the contacts T2 and B2 of switch 67 opens the path from the winding of relay 73 to the output terminal 89, thereby deenergizing the relay 73. The lever 70 is, however, retained in its dotted line position despite the deenergization of the relay 73 for the reason that the beveled end 74 of lever 70 was engaged by the latch rod 75, as shown in dotted lines. With lever 70 in the upper position, the bar 40 76 is also raised into uppermost position, in which position it is in the path of the projection 77 on the cam 52. Therefore, as cam 52 completes its revolution, the projection 77 bears against the upper end of the bar 76 and moves it to the right, 45 as shown in dotted lines, thereby shifting the bellcrank lever 79, through the link 78, into the position shown in dotted lines, in which position the end 81 of lever 79 engages with the projection 62 on shaft 61 and stops the rotation of the entire 50 mechanism. The transmitter remains in the position last described until the subscriber's supervisory panel circuit associated therewith is restored to normal condition thereby energizing the relay 6. Energization of this relay closes its contacts T and F to again supply current from battery 18 over contacts T1 and F1 of switch 67 to the winding of relay 65, causing the latter to operate and pull its armature 66 into the position shown in full lines. Armature 66, when attracted, pulls 55 the latch rod 75 out of engagement with the beveled end 74 of lever 70, thereby permitting the latter to drop into the normal position shown in full lines. At the same time bar 76 drops away from the projection 77 on cam 52, permitting the bellcrank lever 79 to rotate into the position shown 60 in full lines and release the projection 62. The projection 62, however, after being released by the end 81 of the bellcrank lever 79, can move through only a quarter-revolution as the movement of the armature 66 on relay 65 into its full 65 position, moved the pawl 63 on bellcrank lever 64 into position to engage the projection 62. The completion of the foregoing operation restores the transmitter to the starting position, in which it 70 is ready to receive and transmit another alarm.

It will have been observed that following the release of relay 65 in response to an alarm, the contacts T1 and F1 of switch 67 were opened, thereby permanently opening the energizing circuit of relay 65 and completely disconnecting it from the subscriber's supervisory panel. This insures that once the relay 6 in the subscriber's supervisory panel circuit releases, the transmitter will automatically function to transmit an alarm regardless of re-energization of the relay 6. The contacts T1 and F1, however, are closed by the lever 68 following the transmission of an alarm code so that the transmitter will thereafter be automatically restored to normal operating condition in response to energization of the relay 6 in the subscriber's supervisory panel circuit. 15

The spring motor 50 is designed to rotate the cam 52 through many revolutions in response to a single winding. Under ordinary conditions the line finder, associated with the transmitter, 20 will seize an idle line to fire or police headquarters before the cam 52 completes a fifth of a revolution so that the alarm code will be transmitted and the transmitter shut down as described at the completion of the first revolution 25 of the cam 52. However should for any reason all of the lines to fire or police headquarters be busy or out of order so that the line finder LF has not seized a line at the end of one revolution of cam 52, the cam will continue to revolve 30 until the spring motor 50 is run down or until an idle line to fire or police headquarters is available because the relay 73 receives its energizing current to shut down the transmitter from the headquarters line supervisory panel battery and therefore cannot be energized until an idle line has been seized by the line finder. This characteristic of the transmitter insures its proper performance to transmit an alarm, even under the most adverse conditions that may obtain in practice. 35

Function and operation of equipment in the headquarters line supervisory panels

As shown in Fig. 1, each line HL extending 45 from the central station CS to the fire or police headquarters SD terminates at the central station end on a headquarters line supervisory panel HP. The primary function of this supervisory panel HP is to detect and indicate the existence 50 of trouble on its associated headquarters line and prevent the line from being seized by a line finder in case the line is out of order. Certain elements of the headquarters line supervisory panel HP have previously been described in connection with the operation of the code transmitter T. 55

Referring now to Fig. 9, it will be observed that the line HL extending to fire or police headquarters SD terminates in the supervisory panel 60 HP. One line conductor 106 is connected through a resistor 108 directly to ground. The other line conductor 107 is normally connected through the winding of an alarm recorder pulsing relay 103, contacts B2 and T2 of a holding relay 100 and the windings of a marginal relay 102 and a sensitive relay 101 to battery 99. At police or fire headquarters the line conductors 106 and 107 are connected in series with a tamper switch 109 and the pulsing relay 105 of the alarm recorder at 70 the fire or police headquarters. The alarm recorder at the station SD has not been shown in Fig. 9 but it is to be understood that it may be similar to the alarm recorder 104 shown on the headquarters line supervisory panel HP. Thus 75

it will be observed that the code recorder 104 is connected in series with the contacts of the pulsing relay 103 and the battery 99. Likewise the contacts of the pulsing relay 105 in the alarm recorder AR at the fire or police headquarters SD 5 may be connected to a suitable source of current through the contacts of the pulsing relay 105. The remaining elements shown in Fig. 9 will be described in connection with the operation of the circuit.

10 In Fig. 9 the circuit under normal conditions of the line HL is shown in heavy lines and has been previously traced. Current from battery 99 flows continuously through this heavy line circuit and is limited to a predetermined normal value by the resistance 108 connected in series 15 between line 106 and ground and the resistance of the pulsing relay 105 at the fire or police headquarters. Marginal relay 102 is so adjusted that 20 it does not operate in response to this normal current. On the other hand, the sensitive relay 101 is maintained in operative condition by normal current.

Now assume that a ground occurs on the line 25 conductor 106. This ground in effect shunts out the resistor 108, thereby permitting an increase in the current flow through the circuit sufficient to operate the marginal relay 102. This relay 102 upon operating closes its contacts F2 and T2 30 to connect a signal lamp 110 and a buzzer 111 across battery 112. Thus the circuit may be traced from the grounded side of battery 112 to contact F2 on relay 102, thence to contact T2 on that relay, and thence through a conductor 35 125 and through lamp 110 and/or the buzzer 111 back to battery 112. A switch 113 is provided to break the buzzer circuit and stop its noise until the trouble is repaired but the lamp 110 remains lighted as long as relay 102 is released. 40 The operation of relay 102 also closes contacts F1 and T1 on that relay, completing a path from ground through contacts F1 and T1 on relay 102, thence through a conductor 114, through T1 and B1 of relay 96 to the supervisory contact 90 on 45 the line finder LF, thereby applying ground to the supervisory contact 90. It is to be understood that the contacts 90, 91 and 92 on the line finder LF shown in Fig. 9 are also connected in multiple with similar contacts on each of the 50 other line finders in the system, (these connections being shown schematically in Fig. 1). It has also been previously stated that the circuits of the line finders LF are such that they will not seize a line having ground on its supervisory contact 90. Therefore, so long as a ground exists on the line conductor 106 the lamp 110 remains lighted, indicating to the attendant that the line is in trouble and at the same time ground is maintained on the supervisory contact 90 to prevent a line finder seizing that line.

Should a ground occur on the line conductor 55 107, the same result is obtained. In other words, resistor 108 and the winding of relay 105 are both shunted out of the heavy line circuit, again causing the marginal relay 102 to pull and indicate the existence of the trouble, as previously described.

Should a short occur across line conductors 106 and 107, the marginal relay 102 will again pull 60 to indicate the existence of trouble since a short on the line shunts out the winding of relay 105, thereby permitting sufficient increase in the current in the line to operate relay 102.

Should an open circuit occur on either line 65 conductor 106 or 107, the normal current flow

is interrupted through both the sensitive relay 101 and the marginal relay 102. This causes the release of relay 101, although this relay does not release immediately, because it is of slow release type, to prevent the giving of a trouble 5 indication in response to momentary open circuit conditions on the line. Relay 101 when released completes a circuit from ground over its contacts T2 and B2, to conductor 125, thereby lighting the lamp 110 and ringing the buzzer 111. 10 The release of relay 101 also closes its contacts T1 and B1, completing a path from ground to the conductor 114 and thence over the path previously traced to the supervisory contact 90, thereby grounding supervisory contact 90, as previously described.

The normal operation of the circuit shown in Fig. 9 in response to seizure of the line contacts 90, 91 and 92 by line finder brushes 93, 94 and 95 is as follows: As previously explained, following seizure of a line by the line finder, that line is connected through the line finder to the transmitter associated therewith, causing current to flow from battery 99 through winding 97 on relay 96, out over line contact 91, through the closed circuit in the transmitter, back over line contact 92, through winding 98 on relay 96 to ground. Relay 96 thereupon pulls and supplies current from battery 99 through a current limiting resistor 115 and through contacts T2 and F2 on relay 100, through the winding of the holding relay 100 to ground, thereby operating the holding relay 100. The operation of the holding relay 100 applies ground over its contacts T4 and F4 directly to the supervisory contact 90 to indicate to the other line finders in the system that the line is busy and not in condition for transmission of another alarm. The operation of the holding relay 100 also disconnects the line supervisory relays 101 and 102 at contact T2 on relay 99. 40 At the same time it completes a circuit from the winding of relay 103, over contacts F1 and T1 of relay 100, to the back contact B2 on relay 96. Following the disconnection of the supervisory relays 101 and 102 from the line circuit the sensitive relay 101 releases. This closes the contacts associated with relay 101 to light the lamp 110, ring the buzzer 111 and apply ground to conductor 114. The application of ground to conductor 114, however, is not effective to ground the supervisory contact 90 because the contacts T1 and B1 on relay 96 are open. It is for this reason that the separate grounding path to contact 90 is provided over the contacts T4 and F4 of the holding relay 100. It will have been observed 55 that the opening of contacts T2 and B2 on the holding relay 100 when the latter pulled completely disconnected the relays 101 and 102 from the line circuit HL so that those relays cannot be actuated during the transmission of an alarm 60 over the line.

Following the seizure of the line by the line finder, the transmitter associated with that line finder successively opens the line circuit at its coding contacts to transmit an alarm code. Relay 96 is a fast operating and fast release relay 65 so that it releases and pulls each time its circuit is interrupted. The resulting movement of the transfer contact T2 on relay 96 successively interrupts the current flowing from battery 99 over contacts T2 and B2 on relay 96 and over contacts T1 and F1 of the holding relay 100, through the winding of the local alarm recorder pulsing relay 103 and through the alarm recorder pulsing relay 105 at fire or police headquarters, 70 75

thereby causing the recordation of the transmitted code on the recorders. Each time the transfer contact T2 on relay 96 opens from contact B2, it closes on contact F2 to supply current to the winding of the holding relay 100. The latter relay is of a slow release type so that it holds up continuously in response to intermittent pulses of current supplied by the relay 96.

After the transmitter has completed transmission of its code, it releases in a manner heretofore described and opens the circuit extending through the line finder to the brushes 94 and 95. The relay 96 thereupon remains released for a prolonged period of time, causing the release of the holding relay 100. The release of relay 100 reconnects the supervisory relays 101 and 102 in series with the line conductor 107 at contacts T2 and B2 on the holding relay 100. The sensitive relay 101 thereupon pulls and the complete circuit is restored to normal condition shown in Fig. 9 ready to transmit another alarm code should its associated line be seized by a line finder or to indicate the existence of trouble should trouble occur on either one of the line conductors 25 106 and 107.

Although my invention has been described with reference to certain specific circuit arrangements and apparatus, it is to be understood that the principles involved may be incorporated in other apparatus and circuits differing from those specifically described. The invention, therefore, is to be limited only as set forth in the appended claims.

I claim:

- 35 1. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged period of time, means at said control station for maintaining connection between one side of said line through said device to ground and maintaining connection between the ungrounded terminal of said source and the other side of said line in response to continuous current flow from one side of the line into said control station and for connecting said device in series between said source and both sides of said line and for producing a trouble indication in response to interruption of current flow from said one side of the line into the control station, means responsive to current flow in excess of said normal value from said control station into said one side of said line for opening said one side of said line at the control station end thereof, means at said premises station for maintaining connection between both sides of said line through said loop in response to normal current flow through said line and loop and for connecting said loop between said line and ground conductor in response to interruption of said normal current flow, and means at said premises station for permanently opening said loop in response to danger, whereby any increase or decrease in said normal current flow in either side of said line at the control station end produces a trouble indication at said control station and opening of said loop releases said device at said 70 control station to transmit an alarm.

2. An alarm system as described in claim 1 in which said means at the premises station for permanently opening said loop in response to danger comprises means for short circuiting said loop in response to danger, and means responsive to increased current flow through said short circuited loop in excess of normal value for opening said loop.

3. In a signaling system comprising a two conductor metallic line circuit subject to trouble conditions that might decrease the resistance to ground of either side of said line circuit, and having signaling equipment at each end normally bridged across said two conductors, means responsive to a predetermined decrease in the resistance to ground of either one of said line conductors for disconnecting the signaling equipment at each end of the line circuit from that conductor and connecting said equipment between the other line conductor and ground.

4. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm only when said device is deenergized for a prolonged interval of time, means at said control station for maintaining said source and device connected in series between the two sides of said metallic line in response to normal current flow from said source out over one side of said line and back over the other side and for connecting said source and device in series between ground and both sides of said line in response to interruption of said normal current flow, means at said premises station for maintaining connection between one side of said loop and one side of said line in response to continuous current flow therebetween, and for transferring said one side of the loop from connection to said one side of the line to connection to said ground conductor in response to interruption of said current flow over one side of the line at the premises end, means connecting the other side of said loop to the other side of said line, and means at said premises station for permanently opening said loop in response to danger, whereby said device at the control station is deenergized for a prolonged interval of time to produce an alarm.

5. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and device connected in series between the two sides of said metallic line in response to normal current flow from said source out over one side of said line and back over the other side and for connecting said source and device in series between ground and both sides of said line in response to interruption of said nor- 75

- mal current flow, means responsive to current flow in excess of said normal value from said control station into one side of said line for opening said one side of said line at the control station end thereof, means at said premises station for maintaining connection between one side of said loop and said one side of said line in response to continuous current flow therebetween, and for transferring said one side of the loop from connection with said one side of the line to connection with said ground conductor in response to interruption of current flow over said one side of the line at the premises end, means connecting the other side of said loop to the other side of said line, and means at said premises station for permanently opening said loop in response to danger, whereby said device at said control station is deenergized for a prolonged interval of time to produce an alarm.
6. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and device connected in series between the two sides of said metallic line in response to normal current flow from said source out over one side of said line and back over the other side, and for connecting said source and device in series between ground and both sides of said line in response to interruption of said normal current flow, means at said premises station for maintaining connection between one side of said loop and one side of said line in response to continuous current flow therebetween, and for transferring said one side of the loop from connection with said ground conductor in response to interruption of current flow over said one side of the line at the premises end, means connecting the other side of said loop to the other side of said line, means for switching said loop from connection between ground and the said other side of said line to connection between ground and said one side of said line in response to interruption of current flow from said other side of the line into said premises station, and means at said premises station for permanently opening said loop in response to danger, whereby said device at said control station is deenergized for a prolonged interval of time to produce an alarm.
7. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining connection between one side of said line through said device to ground and maintaining connection between said source and the other side of said line in response to continuous current flow from said one side of the line into said control station and for connecting said device in series between said source and both sides of said line in response to any interruption of current flow from said one side of the line into the control station, means responsive to current flow in excess of said normal value from said control station into said other side of the line for disconnecting said other side of the line from the control station circuit, means at said premises station for maintaining connection between said one side of said loop and one side of said line in response to continuous current flow therebetween, and for transferring said one side of the loop from connection with said one side of the line to connection with said ground conductor in response to interruption of current flow over said one side of the line at the premises end, means connecting the other side of said loop to the other side of said line, means for switching said loop from connection between ground and the said other side of said line to connection between ground and said one side of said line in response to interruption of current flow from said other side of the line into said premises station, and means at said premises station for permanently opening said loop in response to danger, whereby said device at said control station is deenergized for a prolonged interval of time to produce an alarm.
8. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and device connected in series between the two sides of said metallic line in response to normal current flow from said source out over one side of said line and back over the other side, and for connecting said source and device in series between ground and both sides of said line in response to interruption of said normal current flow, means responsive to current flow in excess of said normal value from said control station into said one side of said line for opening said one side of said line at the control station end thereof, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means connecting the other side of said loop to the other side of said line, and means at said premises station for permanently opening said loop in response to danger, whereby said device at said control station is deenergized for a prolonged interval of time to produce an alarm.
9. In an alarm system, a metallic premises detection loop, a remotely located central station, an alarm transmitter at the central station, a two-conductor metallic line between said premises station and the central station, a source of current at the central station, a loop at the premises station having a resistance such that when connected in series with said source it limits the current therefrom to a predetermined normal value, a ground conductor at the premises station, a normally energized electrical device at the central station and means controlled thereby for producing an alarm when said device is deenergized for a prolonged interval of time, means at the central station for maintaining connection between one side of the loop and one side of the line to connection with said ground conductor in response to interruption of current flow over said one side of the line at the premises end, means connecting the other side of the loop to the other side of the line, and means at the premises station for permanently opening said loop in response to danger, whereby said device at the central station is deenergized for a prolonged interval of time to produce an alarm.

ises and central station, a premises supervisory means connecting said detection loop to said line at the premises end, a supervisory means at said central station including means for supplying actuating current to said premises supervisory means and detection loop over said metallic line, switching means in said premises supervisory means responsive to normal current flow in said detection loop for maintaining said detection loop connected in series with said metallic line, said switching means opening the series circuit comprising said line and loop in response to increase in current in said detection loop above a predetermined margin, and means including a normally operated relay in said central station supervisory means and in series with said metallic line for locking said transmitter under normal line conditions and for releasing said transmitter to transmit an alarm in response to opening of said series circuit comprising said line and said loop at said premises end.

10. A system as described in claim 9, in which said current responsive means in the premises supervisory means locks up when actuated to permanently open said line at the premises end and in which said normally operated relay at said central station is slow to release, whereby said transmitter is not released to transmit an alarm by momentary open circuit conditions in said system.

11. In an alarm system, a control station, a premises station, a two-conductor metallic line for interconnecting said stations, a source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial period of time, means at said control station for maintaining said source and alarm producing device connected in series between the two sides of said metallic line in response to normal current flow from said source out over one side of said line and back over the other side, and for connecting said source and alarm producing means in series between ground and both sides of said line following interruption of said normal current flow, means at said premises station for maintaining connection between one side of said line and one side of said loop in response to current flow therebetween and for connecting said one side of said loop to ground in response to interruption of current flow therebetween, means for connecting the other side of said loop to the other side of said line, and means at said premises station responsive to current flow in said loop in excess of said normal value for breaking said connection between said loop and ground, whereby said device is released for a substantial interval of time to produce an alarm.

12. A system as described in claim 11 in which said means at said premises station responsive to current flow in said loop in excess of said normal value locks up in response to current flow in said loop in excess of said normal value, for permanently breaking said connection between said loop and ground.

13. A system as described in claim 11 with means responsive to current flow in said loop in excess of said normal value for opening said loop circuit.

14. A system as described in claim 11 in which said means at said premises station for breaking said connection between said loop and ground in response to current flow in said loop in excess of said normal value comprises a relay connected in series with said loop and having back contacts in series with said loop and relay and other back contacts in series in the path to ground over which said loop is adapted to be connected to ground.

15. A system as described in claim 11 with means for switching said loop from connection between ground and the said other side of said line to connection between ground and said one side of said line in response to interruption of current flow from said other side of the line into said premises station.

16. A system as described in claim 11 with slow release means for switching said loop from connection between ground and the said other side of said line to connection between ground and the said one side of said line in response to interruption for an appreciable interval of time of current flow from said other side of the line into said premises station.

17. In an alarm system, a control station, a premises station, a two-conductor metallic line for interconnecting said stations, a source of current, a loop at said premises station having a resistance such that when connected in series with said source it limits the current therefrom to a predetermined normal value, means for reducing the resistance of said loop in response to danger, a normally energized, electrical device at said control station and means controlled thereby for producing an alarm when said device is deenergized for an appreciable interval of time, said loop comprising two conductors connected together through a resistor, means for connecting said loop conductors at one end to said line, means for interconnecting the opposite ends of each loop conductor in response to interruption of current flow in said loop, and means responsive to current flow in said loop in excess of said normal value for permanently opening said line, whereby said device at the control station is released for a substantial interval of time to produce an alarm.

18. A system as described in claim 11 in which said loop comprises two conductors connected together through a resistor, with means for interconnecting the opposite ends of each loop conductor in response to interruption of current flow in said loop.

19. A system as described in claim 11 in which said loop comprises two conductors connected together through a resistor and in which said means at said premises station for maintaining connection between one side of said line to one side of said loop in response to current flow therebetween and for connecting said side of said loop to ground in response to interruption of current flow therebetween, comprises a relay, and means including contacts on said relay for interconnecting the opposite ends of each loop conductor in response to interruption of current flow in said relay.

20. In an alarm system, a control station, a premises station, a two-conductor metallic line for interconnecting said stations, a source of current at said control station, a loop at said premises station having a resistance such that when connected in series with said source it limits the current therefrom to a predetermined normal value, means for reducing the resistance of said loop in response to danger, a normally energized

- electrical device at said control station and means controlled thereby for producing an alarm when said device is deenergized for a substantial period of time, means at said premises station for maintaining connection between one side of said loop and one side of said line in response to continuous current flow therebetween, and for transferring said one side of the loop from connection to said one side of the line to connection 5 to ground in response to interruption of current flow therebetween, means for connecting the other side of said line to the other side of said loop, means responsive to current flow in excess of said normal value from said control station 10 into said one side of said line for opening said one side of said line at the control station end thereof, means at said control station for maintaining said source and device connected in series between the two sides of said metallic line in response to normal current flow from said source out over one side of said line and back over the other side, and for connecting said source and device in series between ground and both sides of said line following interruption of said normal current flow, 15 and means at said premises station responsive to current flow in said loop in excess of said normal value for breaking said connection between said loop and ground, whereby said device is released for a substantial interval of time to produce an 20 alarm.
21. In an alarm system, a control station, a premises station, a two-conductor metallic line for interconnecting said stations, a source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial period of time, means at said premises station for maintaining connection between one side of said loop and one side of said line in response to continuous current flow therebetween, and for transferring said one side of the loop from said one side of the line to ground in response to interruption of current flow therebetween, means for connecting the other side of said loop to the other side of said line, means responsive to current flow in excess of normal value in the control station end of either side of said line for opening that side of the line, and means responsive to current flow in excess of said normal value in both sides of said line from said control station for opening only said one side of the line, means at said control station for maintaining said source and device connected in series between the two sides of said metallic line in response to normal current flow from said source out over one side of said line and back over the other side, and for connecting said source and device in series between ground and both sides of said line following interruption of said normal current flow, and means at said premises station responsive to current flow in said loop in excess of said normal value for breaking connection between said loop and ground, whereby said device is released for a substantial interval of time to produce an alarm.
22. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial period of time, means at said control station for maintaining connection between one side of said line through said device to ground and maintaining connection between said source and the other side of said line in response to continuous current flow between said one side of the line and said control station, means for connecting said device in series between said source and both sides of said line in response to interruption of current flow from said one side of the line into the control station, means at said premises station for maintaining connection between one side of said loop and said one side of said line in response to continuous current flow therebetween, means for transferring said one side of the loop from connection with said one side of the line to connection with ground in response to interruption of current flow between said loop and line, means for connecting the other side of said loop to the other side of said line, means responsive to current flow in excess of said normal value between said control station and said one side of said line for opening said one side of said line at the control station end thereof, and means at said premises station responsive to current flow in said loop in excess of said normal value for breaking connection between said loop and ground, whereby said device is released for a substantial interval of time to produce an alarm in response to danger.
23. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial interval of time, means at said control station for maintaining connection between one side of said line through said alarm producing device to ground and maintaining connection between said source and the other side of said line in response to continuous current flow from said one side of the line into said control station and for connecting said alarm producing device in series between said source and both sides of said line in response to interruption of current flow from said one side of the line into the control station, means responsive to current flow in excess of said normal value from said control station into said other side of the line for disconnecting that line from the control station circuit, means at said premises station for maintaining connection between said one side of said line and one side of said loop in response to current flow therebetween and for transferring said one side of said loop from connection with said one side of said line to connection to ground in response to interruption of current flow therebetween, means for maintaining connection between the other side of said line and the other side of said loop in response to current flow therebetween and for disconnecting said other side of said line from

said loop in response to interruption of current therebetween, means for switching said loop from connection between ground and the said other side of said line to connection between ground and said one side of said line in response to interruption of current flow from said other side of the line into said premises station, and means at said premises station responsive to current flow in said loop in excess of said normal value for breaking said connection between said loop and ground, whereby said device is released for a substantial interval of time to produce an alarm.

24. An alarm system as described in claim 23 in which said means for switching said loop from connection between ground and the said other side of said line, to connection between ground and said one side of said line, is a slow release device.

25. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial period of time, means at said control station for maintaining connection between one side of said line through said alarm producing device to ground and maintaining connection between said source and the other side of said line in response to continuous current flow from said one side of the line into said control station and for connecting said alarm producing device in series between said source and both sides of said line in response to interruption of current flow from said one side of the line into the control station, means responsive to current flow in excess of said normal value from said control station into said other side of the line for disconnecting that side of the line from the control station circuit, means at said premises station for maintaining connection of said loop across said line in response to continuous current flow between said line and loop and for connecting said loop between ground and the said other side of said line in response to interruption of current flow between said line and loop, means for reversing connections of said loop to said line and ground in response to cessation of current flow over the other side of said line into said premises station, and means responsive to current flow in excess of said normal value from said control station into said one side of said line for opening said one side of said line at the control station end thereof, whereby said device is released for a substantial interval of time to produce an alarm.

26. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial interval of time, means at said control station for maintaining connection be-

tween one side of said line through said alarm producing device to ground and maintaining connection between said source and the other side of said line in response to continuous current flow from said one side of the line into said control station and for connecting said alarm producing device in series between said source and both sides of said line in response to interruption of current flow from said one side of the line into the control station, means at said premises station for maintaining connection between one side of said loop and one side of said line in response to continuous current flow therebetween, and for transferring said one side of the loop from said one side of the line to ground in response to interruption of current flow therebetween, means responsive to current flow in excess of said normal value from said control station into said other side of the line for disconnecting said other side of the line from the control station circuit, means for maintaining connection between the other side of said line and the other side of said loop in response to current flow therebetween and for disconnecting said other side of said line from said loop in response to interruption of current flow therebetween, means for reversing connections of said loop to said line and ground in response to interruption of current flow over the other side of said line into said premises station, means for switching said loop from connection between ground and the said other side of said line to connection between ground and said one side of said line in response to prolonged interruption of current flow from said other side of the line into said premises station, and means responsive to current flow in excess of said normal value from said control station into said one side of said line for opening said one side of said line at the control station end thereof, whereby said device is released for a substantial interval of time to produce an alarm.

27. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial interval of time, means at said control station for maintaining connection between one side of said line through said alarm producing device to ground and maintaining connection between said source and the other side of said line in response to continuous current flow from said one side of the line into said control station and for connecting said alarm producing device in series between said source and both sides of said line in response to interruption of current flow from said one side of the line into the control station, means at said premises station for maintaining connection between one side of said loop and said one side of said line in response to continuous current flow over said one side of the line at the premises end and for disconnecting said one side of the line from said loop in response to interruption of current over said one side of the line at the premises end, means at said premises for connecting said other side of said line to the other side of said loop, and means responsive to current flow in

excess of said normal value from said control station into said other side of the line for disconnecting that line from the control station circuit, whereby said device is released for a substantial interval of time to produce an alarm in response to a reduction in the resistance of said loop.

28. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, means for reducing the resistance of said loop in response to danger, a normally energized electrical device at said control station and means controlled thereby for producing an alarm when said device is deenergized for a substantial interval of time, means at said control station for maintaining connection between one side of said line through said alarm producing device to ground and maintaining connection between said source and the other side of said line in response to continuous current flow from said one side of the line into said control station and for connecting said alarm producing device in series between said source and both sides of said line in response to interruption of current flow from said one side of the line into the control station, means at said premises station for maintaining connection between one side of said loop and said one side of said line in response to continuous current flow over said one side of the line at the premises end and for disconnecting said one side of the line from said loop in response to interruption of current over said one side of the line at the premises end, means for maintaining connection between the other side of said line and the other side of said loop in response to current flow therebetween and for opening said other side of said line at the premises end in response to prolonged interruption of current therebetween, means for switching said loop from connection with the said other side of said line to connection with said one side of said line in response to prolonged interruption of current flow from said other side of the line into said premises station, means responsive to current flow in excess of normal value into either side of said line at the control station end for opening that side of the line, and means responsive to current flow in excess of said normal value into both sides of said line from said control station for opening only said one side of the line.

69 29. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining connection between one side of said line 70 through said alarm producing device to ground and maintaining connection between said source and the other side of said line in response to continuous current flow from said one side of the line into said control station and for connecting said alarm producing means in series 75

between said source and both sides of said line in response to interruption of current flow from said one side of the line into the control station, means at said premises station for maintaining connection between one side of said loop and said one side of said line in response to continuous current flow over said one side of the line at the premises end and for disconnecting said one side of the line from said loop in response to interruption of current flow over said one side of the line at the premises end, means at said premises for connecting the other side of said loop to the other side of said line, and means responsive to current flow in excess of said normal value from said control station into said other side of the line for disconnecting said line from the control station circuit, whereby said device is deenergized for a prolonged interval of time to produce an alarm in response to a ground on the said other side of said loop.

30. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining connection between one side of said line through said alarm producing device to ground and maintaining connection between said source and the other side of said line in response to continuous current flow from said one side of the line into said control station and for connecting said alarm producing means in series between said source and both sides of said line in response to interruption of current flow from said one side of the line into the control station, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means responsive to current flow in excess of said normal value from said control station into said other side of the line for disconnecting said line from the control station circuit, means for maintaining connection between the other side of said loop and the other side of said line in response to normal current flow therebetween and for switching said loop from connection between ground and the said other side of said line to connection between ground and said one side of said line in response to interruption of current flow from said other side of the line into said premises station, and means responsive to current flow in excess of said normal value from said control station into said one side of said line for opening said one side of said line at the control station end thereof, whereby said device is deenergized for a prolonged interval of time to produce an alarm in response to a ground on said other side of said loop.

31. In an alarm system, a control station, a premises station, a two-conductor metallic line for interconnecting said stations, a grounded source of current at said control station, a loop 75

at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining connection between one side of said line through said alarm producing device to ground and maintaining connection between said source and the other side of said line in response to continuous current flow from said one side of the line into said control station and for connecting said alarm producing means in series between said source and both sides of said line in response to interruption of current flow from said one side of the line into the control station, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means for maintaining connection between the other side of said loop and the other side of said line in response to normal current flow therebetween and for switching said loop from connection between ground and the said other side of said line to connection between ground and said one side of said line in response to interruption of current flow from said other side of the line into said premises station, means responsive to current flow in excess of normal value into the control station end of either side of said line for opening that side of the line, and means responsive to current flow in excess of said normal value into both sides of said line from said control station for thereafter reconnecting said other side of the line to said control station circuit, whereby said device is deenergized for a prolonged interval of time to produce an alarm, in response to a ground on the said other side of said loop.

32. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of said normal current flow, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line to the premises

end, means for connecting the other side of said loop to the other side of the line, and means at said control station for deenergizing said device in response to flow of current from said source in excess of said normal value.

33. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of said normal current flow, means at said control station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means for connecting the other side of said loop to the said other side of said line, and means responsive to current flow in excess of normal value into the control station end of either side of said line for opening that side of the line, and means responsive to current flow in excess of said normal value into both sides of said line from said control station for thereafter reconnecting said other side of the line to said control station circuit, and means at said control station for deenergizing said device in response to flow of current from said source to said line in excess of said normal value.

34. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of said normal current flow, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line to the premises

- flow over said one side of the line at the premises end, means for maintaining connection between the other side of said loop and the other side of said line in response to normal current flow therebetween and for switching said loop from connection between ground and the said other side of said line to connection between ground and said one side of said line in response to interruption of current flow from said other side of the line into said premises station, means responsive to current flow in excess of said normal value from said control station into said one side of said line for opening said one side of said line at the control station end thereof, whereby said device is deenergized in response to an open circuit condition on said other side of said line followed by a short on said loop. 5
35. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of said normal current flow, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means at said premises station for connecting the other side of said loop to the said other side of said line, means responsive to current flow in excess of said normal value from said control station into said other side of the line for disconnecting said line from the control station circuit, whereby said device is deenergized in response to an open circuit condition on said one side of the line followed by a short on said loop. 10
36. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of current flow from said one side of the line followed by a short on said loop. 15
37. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining connection between one side of said line through said alarm producing device to ground and maintaining connection between said source and the other side of said line in response to continuous current flow from said one side of the line into said control station and for connecting said alarm producing means in series between said source and both sides of said line in response to interruption of current flow from said one side of the line into the control station, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means responsive to current flow in excess of normal value into the control station end of either side of said line for opening that side of the line, and means responsive to current flow in excess of said normal value into both sides of said line from said control station for thereafter reconnecting said other side of the line to said control station circuit, means for maintaining connection between the other side of said loop and the other side of said line in response to normal current flow therebetween and for switching said loop from connection between ground and the said other side of said line to connection between ground and said one side of said line in response to interruption of current flow from said other side of the line into said premises station, and means at said control station for deenergizing said device in response to an increase in current flow from said source to said line in excess of said normal value. 20
38. In an alarm system, a control station, a premises station, a two-conductor metallic line for interconnecting said stations, a grounded source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of current flow from said one side of the line followed by a short on said loop. 25

- that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining connection between one side of said line through said alarm producing device to ground and maintaining connection between said source and the other side of said line in response to continuous current flow from said one side of the line into said control station and for connecting said alarm producing means in series between said source and both sides of said line in response to interruption of current flow from said one side of the line into the control station, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means for connecting the other side of said loop to the other side of said line, means responsive to current flow in excess of normal value into the control station end of either side of said line for opening that side of the line, and means responsive to current flow in excess of said normal value into both sides of said line from said control station for thereafter reconnecting said other side of the line to said control station circuit, and means at said control station for deenergizing said device in response to an increase in current flow from said source to said line in excess of said normal value.
39. In an alarm system, a control station, a premises station, a two-conductor metallic line for interconnecting said stations, a source of current at said control station, a loop at said premises station having a resistance such that when connected in series with said source it limits the current therefrom to a predetermined normal value, a ground conductor at said premises station, a normally energized electrical device at said control station and means controlled thereby for producing an alarm when said device is deenergized for a prolonged interval of time, means at said control station for maintaining said source and alarm producing device connected in series between the two sides of said metallic line in response to normal current flow from said source out over one side of said line and back over the other side, and for connecting said source and alarm producing means in series between ground and both sides of said line in response to interruption of said normal current flow, means at said premises station for maintaining connection between one side of said loop and one side of said line in response to continuous current flow therebetween, and for transferring said one side of the loop from connection with said one side of the line to connection with said ground conductor in response to interruption of current flow over said one side of the line at the premises end, means for maintaining connection between the other side of said loop and the other side of said line in response to normal current flow therebetween and for switching said loop from connection between ground and the said other side of said line to connection between ground and said one side of said line in response to inter-
- ruption of current flow from said other side of the line into said premises station, means responsive to cessation of current in said loop circuit for a prolonged interval of time for connecting said one side of said line to ground at the premises end, means responsive to current flow in excess of said normal value from said control station into said one side of said line for opening said one side of said line at the control station end thereof, and a marginal relay at said control station connected in series with said source for producing an alarm when operated, said relay being non-operable on said normal current flow, but capable of holding up on said normal current flow, and operating in response to current flow in excess of said normal value, whereby an alarm is transmitted in response to opening of said loop irrespective of a resistance bridge across said line conductors.
40. An alarm system as described in claim 39 in which said means responsive to cessation of current in said loop circuit for a prolonged interval of time for connecting said one side of said line to ground at the premises end comprises a slow release relay connection in series in said loop circuit, the winding of said relay constituting the current limiting resistance in said loop to limit the current therethrough to a predetermined normal value.
41. In an alarm system, a premises station, a control station, and a line interconnecting said stations, a pair of protection loops at said premises station and means for opening the loops in response to danger, means at said premises station including a key operable in one position to connect one of said loops in series with said line and operable in another position to connect the other of said loops in series with said first loop, said key opening said line during movement from one position to the other, signaling means at said premises station responsive to alternating current and means including said key for completing an A. C. circuit between said signaling means and said line when said key is in one only of said two positions, means at said control station for normally supplying direct current to said line, means at said control station responsive to interruption of direct current over said line for producing a signal, and means at said control station for applying alternating current to said line.
42. In an alarm system, a premises station, a control station and a line interconnecting said stations, a pair of protection loops at said premises station and means for opening the loops in response to danger, means at said premises station including a key operable in one position to connect one of said loops in series with said line and operable in another position to connect the other of said loops in series with said line, said key opening said line during movement from one position to the other, signaling means at said premises station responsive to alternating current and means including said key for completing an A. C. circuit between said signaling means and said line when said key is in one only of said two positions, means for maintaining connection between said line and one of said loops through said key in response to direct current flow between said line and loop including a relay connected in series with said line and loop over front contacts on said relay, said contacts permanently opening the operating circuit of said relay in response to interruption of current through the relay, means at said control station for normally supplying

5 direct current over said line to hold said relay operated, means at said control station responsive to predetermined variations in the normal direct current flow to said line for producing an alarm, means at said control station for applying alternating current to said line to restore said relay at the premises station and produce a signal at said premises station when said key is in one of its two positions, and means including 10 a condenser for completing a restoring circuit for said relay independent of the contacts of said relay.

15 43. In a signaling system comprising a two-conductor metallic line subject to trouble conditions that might increase the impedance of either of said conductors, signaling means at each end of said line normally bridged across said line, said means at one end including a source of current for energizing said line, and transfer means responsive to a predetermined increase in the impedance of either of said line conductors for transferring said means at said one end of said line from bridged connection thereto to connection between ground and the other line conductor, and said signaling means at the other end of said line including means responsive to a predetermined decrease in the current flow in either line conductor at the said other end for disconnecting said signaling means at the other end of the line from that line conductor and connecting it between the said other line conductor and ground.

20 44. In a signaling system comprising a two-conductor metallic line subject to trouble conditions that might decrease the impedance between the two conductors of said line, signaling means at each end of said line normally bridged across said line, said means at one end including a source of current for energizing said line, and transfer means directly responsive to a predetermined decrease in the impedance between the two conductors of said line for transferring said means at said one end of said line from bridged 25 connection thereto to connection between ground and one of said line conductors, said signaling means at the other end of said line including means responsive to a predetermined decrease in the current flow in said line at said other end for transferring said signaling means from bridged

connection to said line to connection between one of the line conductors and ground.

5 45. In a signaling system comprising a two-conductor metallic line subject to trouble conditions that might decrease the impedance to ground of either of the conductors, signaling means at each end of said line normally bridged across said line, said means at one end including a source of current for energizing said line, and transfer means responsive to a predetermined decrease in the impedance to ground of either of said line conductors for disconnecting said signaling means at said one end of said line from that line conductor and connecting it between ground and the other line conductor, and said signaling means at the other end of said line including means responsive to a predetermined decrease in the current flow in either line conductor at the said other end for disconnecting said signaling means at the other end of the line from that line conductor and connecting it between the other line conductor and ground.

10 46. In an electric alarm system, a premises station, a remotely located central station, a two-conductor metallic line connecting said stations, a source of current at the central station, means for normally maintaining closed electric circuits between the two conductors of said line at the central station and at the premises station, respectively, and maintaining predetermined normal current flow from said source through said circuits and line conductors, means at said stations quickly responsive to predetermined variations in said predetermined normal current flow for interrupting said first circuits and connecting said source between ground and said line at the central station and connecting said line to ground at the premises station, signaling switch means at the premises station for opening said ground connection at the premises station, alarm producing means at the central station, and means at said central station responsive to prolonged interruption of current flow from said source for actuating said alarm producing means.

15 47. A system as described in claim 46, including means at the central station responsive to current flow from said source in excess of normal value for a prolonged interval of time for actuating said alarm producing means.

FELIX F. DENZLER. 50
